UNITED STATES PATENT OFFICE

2,690,660

KNITTING MACHINE

Max C. Miller, deceased, late of Cumberland, R. I.,
by Ida L. Miller, executrix, Cumberland, R. I.

Application January 24, 1950, Serial No. 140,232

54 Claims. (Cl. 66—96)

1

The present invention relates to straight or full fashioned hosiery knitting machines and more particularly to a means and to a method for automatically performing the weltting operations in producing multi-ply sections in knitted fabrics, such as flat stocking fabrics.

It is a principal object of the present invention to provide a novel and improved welt mechanism for use in full fashioned hosiery machines which will be simpler and more compact in construction and readily embodied in a machine of standard type with a minimum displacement of the usual operating mechanisms of such machines, and which is well adapted for operation in a combination with the several knitting mechanisms of these machines in a fully automatic manner to produce a welt fabric, including the setting up of an initial course of welt fabric, the knitting and folding of the welt fabric, and the topping of the initial welt course on another course on the needles to close the welt. The welt mechanism which forms the subject matter of the invention is provided with welt instrumentalities for setting up the initial course of the welt fabric and for topping the loops of the initial course back on the needles which are substantially similar in construction and in operation to those illustrated and described in the patent to Lieberknecht, No. 2,269,463.

The present invention is in many respects intended as an improvement on the constructions and arrangements of parts illustrated and described in the Lieberknecht patent referred to.

It is a further object of the invention to improve the construction and organization of the welt and knitting mechanisms of the machine acting in combination with one another, and of the control devices associated therewith for the more efficient knitting of the welt and associated leg and foot portions of the stocking blank.

The welt mechanism herein disclosed as embodying in a preferred form the several features of the invention is of the general type comprising a series of welt hooks with vertical shank portions and upwardly turned hooks grooved along their outer edges, spaced for the making of an alternate needle setup. The hooks have imparted thereto vertical and forward and back movements with relation to the needles during the knitting of the setting up course to press off from alternate needles and thereafter to engage in the hooks the alternate needle wale kinks of yarn. Subsequently the welt hooks are again moved with relation to the needles to transfer initial setting up course back to the needles to close the welt.

2

In accordance with the present invention the supporting and actuating structure for the welt hooks comprises for each knitting section of the machine a series of rearwardly extending support levers which are carried on a pivot shaft located some distance beneath and forwardly of the work table of the machine, and a pair of upwardly extending welt hook support arms which are supported for forward and back movement about pivotal connections with the welt support levers above referred to. The movement of the horizontal levers in a vertical plane and of the welt hook support arms in a forward and back direction is controlled by means of cams on a welt cam shaft which is disposed beneath and slightly to the rear of the work table and above the main cam shaft of the machine. The required vertical motions are imparted to the welt hooks by means of cam levers rigidly secured to the horizontal welt lever supporting rock shaft and arranged to extend beneath the welt cam shaft. The vertical position of the welt hooks is further controlled during that portion of the welt knitting subsequent to the knitting of the initial setting up course by means of cooperating detent and latch levers which are automatically controlled to determine the vertical level of operation of the welt hooks during each of the several successive stages of the welt knitting. For imparting forward and back movements to the welt supporting arms and welt hooks carried thereby, cam and follower connections are provided which include a rock shaft disposed rearwardly of the work table, cam and follower levers depending from and yieldably connected to rotate the rock shaft and pusher lever arms which are secured to the rock shaft, and act against the respective welt hook supporting arms to move them in a rearward direction. The construction and arrangement of the welt forward and back motion cam and follower connections is such that a yieldable force only is applied to move the welt hook support arms and welt hooks in the rearward direction. In order to provide for a more accurate and dependable control for the positioning of and movement of the welt hooks in a forward and back direction particularly during the knitting of the setting up course, there is provided a novel backing up device for the welt hooks which acts against the welt support arms at substantially the welt hook level. This backing up mechanism consists of a series of backing up plates which are mounted between and at the ends of the several knitting sections on upwardly extending lever arms secured to a rock shaft which also

has secured thereto one or more downwardly extending cam levers for engagement with co-operating cams on the welt cam shaft. The backing up cam levers and plates are positioned during the setting up course to provide a positive support for the welt hooks during the operation of pressing off the needle kinks from alternate needles and are thereafter again rendered operative to control the forward and back position of the welt hooks during the forward and downward movement of the hooks to push forwardly and to engage the cast-off bars of yarn in the hooks.

In accordance with a feature of the invention, a novel and improved organization of the several operating shafts of the machine is provided which includes the location of the front catch bar motion rock shaft of the machine, together with the associated supporting arms and cam levers rearwardly of the main cam shaft substantially above the rear lower rail of the machine, in order to provide adequate space for the welt cam shaft in the preferred location beneath the work table and above the main cam shaft.

Further in accordance with the invention the several welt bars along the length of the machine are connected with and are mounted on the supporting arms in such a manner as to permit any one of the welt bars to be readily removed by the operator to gain ready access to underlying parts and thereafter to be replaced by the operator in an accurately adjusted position on the lever arms.

In the illustrated machine each welt bar has secured to the middle portion thereof an upwardly extending arm which is arranged to be engaged between two relatively stationary set screws carried by the picot bar supporting shaft from the narrowing machine for accurately positioning the several welt hooks with the co-operating needles when the hooks are moved forwardly into operative relation to the needles in the course of the operations of setting up an initial course of welt fabric and subsequently of transferring the initial course of loops back to the needles to close the welt. The center aligning of the individual welt bars in the manner above described has been found to be a substantial improvement upon the previously employed method of guiding the individual welt bars by means of cams located at opposite ends thereof in that it is simpler and less expensive to manufacture, is capable of easy and accurate adjustment, and is substantially unaffected by expansion or shrinkage of the metal parts as a result of temperature changes.

Further in accordance with the invention the welt devices and the knitting instrumentalities associated therewith are particularly constructed and arranged to form an alternate needle setting up course of small tightly formed loops. The mechanism by means of which these loops are formed, includes a special setting up needle press cam and a special setting up stitch regulator associated therewith, which are rendered operative in the knitting of the setting up course to position the needles so that yarn kinks are formed against the shanks of the needles by the operation of the usual sinkers and dividers which are very substantially smaller than could normally be knitted on the machine. The kinks thus formed may be of a length, for example, in the order of one-half the length of the kinks which would be formed for an ordinary tight stitch on the machine. The welt hooks of the

illustrated machine are particularly constructed and arranged to cooperate with the needles in the formation of the setting up course to press off the yarn kinks thus formed from the alternate needles substantially above the usual press position. During subsequent relative movement of the needles and sinkers as the needles move downwardly toward the knockover, the yarn given up by the cast-off loops is added to the length of the remaining loops which are thus made of a length equal to those formed in the knitting of an ordinary stitch, so that the relative adjustment of needles, sinkers, and knock-over bits for stitch length, as the needles move downwardly past the press and to the knockover position, can remain substantially undisturbed.

Further in accordance with the invention a novel and improved construction and arrangement of the welt wire take-up mechanism is provided which comprises welt wire take-up hooks and endless take-up chains having a yieldable connection with a weighted take-up shaft. The welt wires are arranged to be supported prior to the time that they are required in holders carried on the respective picot bars of the machine. The welt wire take-up mechanism, including the chains and take-up hooks are supported in a pre-set position and cooperate with a dummy movement of the narrowing machine and picot bars to effect an automatic laying in of the welt wires to take up a fold of the welt fabric. During the laying-in operation the picot lateral shift mechanism which would normally operate with the narrowing machine is rendered inoperative.

An automatic device for controlling the operation of and for resetting the welt wire take-up mechanism is provided, which comprises a ratchet and pawl connection actuated from the main cam shaft of the machine when rendered operative to impart a stepped rotational movement to the weighted take-up shaft in the reverse direction to reset the welt wire take-up. The take-up chains and hooks are maintained in their reset position by means of a latch which is actuated by engagement with the welt wire when moved into operative position to release the hooks for engagement with the welt wires. The operation of the resetting pawl and ratchet connection is controlled both to start and stop the resetting operation by movement of the welt wire take-up chains.

In accordance with a feature of the invention a novel thread cutter is provided which is activated automatically in accordance with the dictation of the pattern chain to sever the held end of welt thread at the start of the welt knitting operation. In the preferred form of the device the thread cutter takes the form of a knife arm pivotally mounted on one of the supporting bridges for the welt wire take-up mechanism. The operation of the knife is controlled automatically through dummy movements imparted to the welt wire take-up chains and hooks which cause the knife to be automatically tripped and reset. For tripping the thread cutter into operation, the welt wire take-up relieving mechanism provided with the machine is rendered operative to move the welt wire take-up chains and hooks rearwardly a short distance from the reset position and is then returned to the reset position. The subsequent movement of the welt wire take-up chains and hooks in a forward direction when released to engage the welt wire and to take up the welt fabric, causes the thread cutter to be reset.

In accordance with a feature of the invention the welt wire fabric take-up is arranged to operate during a portion only of the fabric knitting, which includes the knitting of the welt and a portion of the leg. During the knitting of the lower leg and foot, the weight of the welt wire and finished fabric in combination with the action of the nibbed knockover bits here illustrated to clear the fabric as knitted to the backs of the needles has been found adequate to maintain a continued flow of the fabric as knitted into the fabric receiving hoppers.

The automatic step by step return of the welt wire take-up chains and hooks is effected during the knitting of the lower leg and foot of the blank, so that the welt wire take-up will be fully reset prior to the pressing off of the completed set of stocking blanks.

Further in accordance with the invention, mechanism is provided for automatically controlling the operation of the narrowing machine in combination with the welt mechanism including pattern controlled devices for moving the narrowing machine to a high inoperative position for both the setting up and welt loop transfer operations to close the welt, for returning the narrowing machine to the operative position following each of said operations, and for disabling the narrowing machine picot lateral shift during the dummy dipping movement of the narrowing machine and picot bar for the laying in of the welt wires.

In accordance with the invention the knockover bits of the machine are supported and actuated in a novel and improved manner to cause these implements to be spring seated forwardly and downwardly during predetermined portions only of the knitting cycle and at predetermined other portions of the cycle to be positively supported both in the vertical and horizontal direction. In the illustrated machine the knockover bits are mounted on frames provided with pivot pins which engage in downwardly facing semicircular bearings formed in the usual vertically movable knockover bit lever supports. The knockover bit frames and knockover bits supported thereby are tensioned upwardly in said bearings, and forwardly, by suitable tension springs. Adjustable contact screws carried on cam actuated lever arms are arranged to be brought into contact with the underside of the bearing pins so that spring seating in the vertical direction is entirely eliminated and a positive cam controlled movement of the knockover bits is substituted therefor during a portion of each knitting cycle in accordance with the dictation of the actuating cams. A positive control of the vertical position of the knockover bits has been found desirable, particularly during the downward movements of the needles. Thereafter as the needles approach the knocking over level, the pivot pin engaging stop screws are moved downwardly out of contact so that the knocking over of the loops takes place against vertically spring seated knockover bits.

For narrowing operations, a special set of knockover bit actuating cams are provided which function to maintain a positive control of the position of the knockover bits in the vertical plane throughout the entire narrowing cycle.

Further in accordance with the invention a novel and highly organized arrangement of pattern actuated controls is provided in order to provide for a substantially continuous and auto-

matic operation of the machine for the knitting of the welt portion of a knitted stocking blank. These controls, as hereinafter more fully set forth, include a booster mechanism, which is rendered operative in a course preceding each of the setting up and welt transfer courses, and which acts automatically to engage the one revolution welt cam shaft clutch of the machine and after a suitable time lag to shift the welt cam shaft axially, in the first instance to a setting up position, and in the second instance to the welt transfer position.

With the above stated and other objects in view as may hereinafter appear, the several features of the invention consist also of the devices, combinations, and arrangement of parts hereinafter described and claimed, with together with the advantages to be obtained thereby will be readily understood by one skilled in the art from the following description taken in connection with the accompanying drawings, in which:

Fig. 1 is a sectional view looking from the left and taken from the left end of the machine to include portions of the welt mechanism, the narrowing machine, together with the cam shaft control and pattern mechanism illustrated also in front elevation in Fig. 8;

Fig. 2 is a sectional view through the machine looking from the left to illustrate particularly the welt bar supporting and actuating connections;

Fig. 3 is a somewhat fragmentary section of the machine looking from the left on a line 3-3 of Fig. 10 to illustrate particularly the supporting and actuating mechanism for moving the needles, including the special cams for controlling the needle motion during the fabric setting up operation;

Fig. 4 is a somewhat fragmentary vertical section of the machine looking from the left, illustrating particularly the knockover bit supporting and actuating devices shown in front elevation in Fig. 11;

Fig. 5 is a somewhat fragmentary vertical section of the machine looking from the left substantially on a line 5-5 of Fig. 10 and illustrating particularly the special setting up stitch regulator and the mechanism for controlling the vertical movements of the narrowing machine frame, including the mechanisms for moving the narrowing machine to an abnormally high inoperative position and for thereafter automatically returning the narrowing machine to its normal operating position;

Fig. 6 is a somewhat fragmentary vertical section of the machine looking from the left, illustrating particularly the mechanism for controlling the operation of the picot bar shown in front elevation in Fig. 12, and the regulator mechanism shown in front elevation in Fig. 10;

Fig. 7 is a somewhat fragmentary vertical section of the machine illustrating particularly the cam and follower connections for controlling the forward and back movement of the welt bar, the tension relieving mechanism, and the improved catch bar lift mechanism of the machine;

Fig. 8 is a fragmentary detail view in front elevation of a portion of the machine, including the pattern chain racking mechanism, a group of pattern rods controlled from the pattern chain, the main and welt cam shaft shift mechanisms, and the welt cam shaft drive;

Fig. 9 is a somewhat fragmentary detail view in front elevation illustrating the welt bars associated with the two knitting sections together

with the supporting and actuating devices therefor, the picot bars with the welt wires mounted thereon, and the narrowing spindle;

Fig. 10 is a somewhat fragmentary detail view in front elevation illustrating particularly a portion of the main cam shaft of the machine, including the narrowing machine lift mechanism and the main special stitch regulator mechanisms shown in Figs. 5 and 6;

Fig. 11 is a somewhat fragmentary detail view in front elevation illustrating particularly the catch bar lift mechanism, and the knockover bit bar, and the supporting and actuating structure therefor;

Fig. 12 is a somewhat fragmentary detail view in front elevation illustrating particularly the tension relieving mechanism shown in Fig. 7 and the supporting and actuating connections for the picot bar shown in Fig. 6, including a latching mechanism for rendering inoperative the mechanism for imparting the normal lengthwise shifting movement to the picot bar;

Fig. 13 is a fragmentary detail view in front elevation illustrating a portion of the welt cam shaft, one of the welt bars, and the supporting and actuating levers and cams through which the forward and back and vertical movements are imparted to the welt bar;

Fig. 14 is an enlarged fragmentary detail view in front elevation of a welt bar and associated supporting arm illustrating particularly the locking device by which the welt bar is releasably secured to its supporting arms;

Fig. 15 is a plan view of the parts shown in Fig. 14, a portion of the assembly being broken away and sectioned on the line 15—15 of Fig. 14 to illustrate details of the locking device;

35 Fig. 37 is a detail view partly in section taken from the left illustrating particularly the welt hook backing up plate cam;

Fig. 38 is a detail view of the needle setting up draw down cam;

40 Figs. 39—52, inclusive, are a series of similar diagrammatic views in side elevation illustrating particularly the relative positions of the needles, sinkers, and knockover bits and welt hooks for the performance of the setting up operation in which an initial course of welt fabric is set up on the needles and on the welt hooks, the positions of the parts in the several figures being taken for successive angular positions of the cam shaft of the machine;

45 Fig. 53 is a fragmentary plan view of the needles and hooks substantially in the position shown in Fig. 49;

Fig. 54 is a greatly enlarged view of a welt hook;

50 Figs. 55—63, inclusive, are a series of diagrammatic views showing the relative positions of the knitting instrumentalities and welt hooks during the operation of topping the initial course of welt loops back on the needles to close the welt, the degrees of rotation of the main cam shaft of the machine being indicated for each of the relative positions of the parts shown;

55 Figs. 64—71, inclusive, are a series of views showing the operation of the needles, sinkers, and nibbed knockover bits with relation to the press edge to form a knitted course of fabric in which the knockover bits are spring seated both upwardly and down, but are positively controlled during portions of said operation; and

60 Figs. 72—80, inclusive, are a series of views showing the operation of the nibbed knockover bits in combination with the needles, sinkers, and narrowing points for the performance of a narrowing operation.

The machine disclosed in the drawings comprises a multiple section full fashioned knitting

machine, which may be of ordinary description, comprising for each section of the machine a series of spring beard needles 100, which are supported to move as a unit on a needle bar 102 with relation to a fixed press edge 103, individually movable jack sinkers 104, dividers 106, knockover bits 108, and yarn carriers 109 (see Fig. 5) for feeding yarn to the needles. The supporting structure of the machine comprises the usual cross frames 110 located at spaced intervals along the machine length connected by means of longitudinally extended rails which include a sinker rail 112, a lower rear rail 114, a lower front rail 116, and a work table 118. The several cooperating knitting instrumentalities of the machine are driven from a main cam shaft 120 which extends along the length of the machine. The cam shaft 120 is preferably driven from an electric motor, which may be of ordinary description and is not here shown, a motor driven shaft 115 (see Fig. 18), a gear 117 on the shaft, and a driven gear 119 on the cam shaft 120.

In accordance with the usual construction for full fashioned knitting machines, the needle bars 102 (see Fig. 3) associated with the several knitting sections are mounted on frames 121 which are carried for swinging movement toward and away from the press on pivotal mountings 122 on horizontally disposed lever arms 123, rigidly secured to a vertical motion rock shaft 124 extending along the length of the machine. The shaft 124 is provided at intervals with downwardly extending cam levers such as that shown in 125, Fig. 3, each such lever 125 having mounted thereon a roller 126, Fig. 9, for engagement with a vertical motion knitting cam 127 on the cam shaft 120. As best shown in Figs. 9 and 3, there is also provided a needle narrowing vertical motion cam 93, and a special setting up vertical motion cam 91. The setting up vertical motion cam 91 is arranged to be engaged by a cam roller 92 slidably mounted on the pivot stud 93 which also carries the needle vertical motion cam roller 126. Roller 92 is moved into alignment with its cam 91 for the knitting of the setting up course by means of a pattern chain controlled shift rod 94 and a shifter fork 95 secured thereto for engagement with an annular groove in the sleeve hub of cam roller 92.

Operating connections for imparting forward and back motions to the needles comprise for each pair of knitting sections a downwardly extending arm 128 forming part of the supporting frame 121 which is connected by means of a link 129 with a downwardly extending lever arm 130 secured to the needle in and out press motion rock shaft 131 extending along the length of the machine. A tension spring 1230 connected between a rearward extension of link 129 and a bracket on sinker rail 112 tends to swing link 129 and lever 130 in a clockwise direction, as shown in Fig. 3. The shaft 131 is provided at spaced intervals along its length with downwardly extending cam levers 132 each having mounted thereon, (see Fig. 10) a cam roller 133 for engagement with one of three needle in and out cams on the main cam shaft 120, including the usual press cam 134, a narrowing cam 135, and a special setting up course tight stitch press cam 136.

The needle in and out motion cam lever 132 is provided with a downwardly extending portion 137 and a stud 138 which is arranged to be engaged by the usual stitch regulator lever 139 carried on regulator shaft 140 extending along the length of the machine.

A stitch regulator mechanism of ordinary de-

scription which is employed to control the angular position of regulator shaft 140 is shown generally in Figs. 6 and 10 of the drawings. This mechanism comprises a regulator cam lever 141 loosely sleeved on the regulator shaft 140 and having a bifurcated end portion to receive pivot pin 143 on which is slidably mounted a cam roller 144 for engagement with a regulator cam 145. The angular position of regulator shaft 140 with relation to the regulator cam lever 141 is controlled by means of a cooperating lever 146 secured to turn with the regulator shaft 140. The hub of the lever 146 is bifurcated to straddle the hub of the cam lever 141 and is pinned to the regulator shaft. A stop pin 147 adjustably supported on the cooperating lever 146 is arranged for engagement against a cooperating contact surface on the cam lever 141. The regulator shaft 140 together with the levers attached thereto is biased in a counterclockwise direction as viewed in Fig. 6, by means of a heavy tension spring 148 attached to an upwardly extending arm 149. A tension spring 150 connected between the regulator lever 141 and cooperating lever 146 tends to maintain the stop pin 147 in contact with the surface of the cam lever 141.

In accordance with the present invention the knitting instrumentalities and welt setup hooks of the illustrated machine are constructed and arranged to cooperate with one another in a novel manner. In order to provide an alternate needle setting up course which is formed of small loops as compared with the relatively large, open loops which would normally be formed in the knitting of an alternate needle setting up course, it is proposed in accordance with the usual practice to cast off the loops from alternate needles, the yarn which forms these loops being then caught on the welt hooks spaced one for each alternate needle so that the initial setting up course is formed between the intermediate needles and the welt setup hooks. It will be understood that this operation as normally performed would have the effect of producing a setting up course of relatively large loops since the length of yarn from the cast-off loops is added to the length of the intermediate loops remaining.

In accordance with the invention the special setting up press cam above referred to, and a special stitch regulator cooperating therewith are provided which act to position the needles in an abnormally forward position during the yarn sinking operation so that an amount of yarn is measured to the needles which is substantially less than that required for the knitting of the tightest stitch on the particular machine. The very small needle kinks, or half kinks, thus formed are immediately thereafter halved in number and substantially increased in size by the casting off of alternate kinks over the beards of alternate needles as the needles move downwardly, toward the normal press position. Thereafter, as the needles move downwardly past the usual press position to be reformed at the knockover, the lengths of yarn originally kinked about the shanks of alternate needles will be added to the length of the intermediate needle loops thus permitting the needles to move downwardly in a substantially normal manner to the knockover position. The loops of the alternate needle setting up course which are now drawn down by the downward movement of the needles to the knockover and which are engaged by the welt hooks will have the length of a normally tight stitch such as would be formed in the knitting of an ordinary course

In the illustrated construction, a special setting up needle vertical motion cam is employed which acts to move the needles to an abnormally low level at the knockover in order to cooperate most effectively with the loop engaging movements of the welt hooks in the setting up course.

Features of applicant's construction which make possible the knitting of an alternate needle setting up course of small loops include an improved construction and arrangement of the mechanism for moving the welt hooks to obtain a more accurate and positive control of the movements and a special stitch regulator mechanism which is rendered operative to measure the loops formed in the setting up course. The stitch regulation is effected during the knitting of the setting up course by means of the special setting up needle press cam 136 which acts in cooperation with a setting up stitch regulator (see Figs. 5 and 10). The special regulator referred to comprises a special regulator cam 152 which is secured to the main cam shaft 120 and is arranged to be acted upon by roller 153 shiftable on a stud 154 carried by a forked setting up regulator cam lever 155 secured to the regulator shaft 140. The position of the roller 153 is controlled by means of a shifting fork 156 of which the hub portion is loosely sleeved on a pattern shift rod 157. Movement of the shift rod to the right upon a racking of the pattern chain 309 serves to load a spring 158 on the shift rod 157 tending to move the fork 156 and roller 153 yieldably into alignment with the special regulator cam 152. A collar 159 fixed to the rod 157 is arranged for engagement against the right side of the shifter fork hub to effect a return movement of the shifting fork 156 and roller 153 with the rod 157 to the initial inoperative position.

The sinkers 104 and dividers 106 have the usual construction and mode of operation of these parts. The sinkers 104 alternating with the dividers along the length of the knitting section are advanced successively in a knitting wave which follows the traversing stroke of the active yarn carrier along the length of the knitting section. The yarn is thus measured or sunk about the shanks of each alternate pair of needles. The alternating dividers are then advanced, robbing yarn from the adjacent singer loops in order to form an evenly measured row of yarn kinks about the shanks of all the needles. The sinkers are advanced by means of a longitudinally traversing slur-cock cam mechanism which being well known in the art is not here described.

The mechanism for advancing the dividers and for thereafter withdrawing the sinkers and the dividers prior to and during the knocking over of the loops comprises a catch bar 162 (see Fig. 7) which is supported and controlled by means of front and rear catch bar motions to perform the normal functions of a catch bar in these machines. The rear catch bar motion which comprises vertically disposed levers on which the catch bars are pivotally supported for forward and back and for vertical positioning movements is of a form well known in the art and is not here specifically illustrated. For a disclosure of the back catch bar motion, reference may be had to the United States patent to Lieberknecht, No. 2,269,463. The front catch bar motion herein disclosed, which is employed for imparting up and down movements to the catch bar is of a novel and improved construction. As shown in Fig. 7, the catch bar 162 has secured thereto at intervals along its length forwardly extending arms 163

which are supported at their forward ends upon vertically extending front catch bar links 164 pivotally connected at their lower ends to horizontally extending lever arms 165 on a front catch bar rock shaft 166. Operation of the rock shaft 166 is controlled by means of one or more cam levers 167 which may be secured to the shaft at intervals along its length, each having a roller 168 arranged to be acted upon by a front catch bar cam 170 on the main cam shaft 120. The coil spring 172 fastened to the end of cam lever 167 acts to hold the roller 168 at all times in engagement with its cam 170. It will be noted that the front catch bar motion above described is novel in that the front catch bar rock shaft has been moved from its usual location beneath and slightly rearwardly of the machine table 118 to a position above and rearwardly of the lower rear rail 114, being supported from the rail by means of brackets 174. The new arrangement of the front catch bar rock shaft provides a space for a large diameter welt cam shaft and operating cams hereinafter to be described.

The knock-over bits 108 as best shown in Figs. 25 4 and 11 and in Figs. 45 to 68, inclusive, are of the so-called notched type being provided with notches or throats 176 and are rigidly secured in a slotted bar 178 which is fastened to a frame 180. At each end the frame is provided at its lower edge with downwardly extending arms 182 in which are mounted horizontally extending fulcrum pins 184 on which the frame 180 and knock-over bits 108 are pivoted for forward and back movements. Each knock-over bit frame 180 is 30 further supported and guided at each end in a bracket 186 bolted to the sinker rail 112. The brackets 186 prevent endwise movement of the frame and are further provided with cover plates 188 which serve to limit the forward movement 40 of the knock-over bit frame 180 away from the sinker rail 112. The knock-over bit frame 180 and knock-over bit bar 178 are biased in a forward direction by means of tension springs 190 connected between lugs 191 on the knock-over bit frame 180, and adjustable links 192 which are 45 adjustably secured at their forward ends to downwardly extending brackets 194 fastened to the underside of the machine table 118. The position of the knock-over bit frame 180 is controlled forwardly and back against the pressure of springs 190 by means of two upwardly extending arms 196 supported at their lower ends on a rock shaft 198 and arranged at their upper ends to abut against lugs 200 formed on the front 50 face of the knock-over bit frame 180. The arms 196 are adjustably connected to turn with the rock shaft 198 by means of levers 202 rigidly mounted on the shaft 198 and at their upper ends connected by adjustable screws 204 to the arms 196. Oscillatory movements are imparted to rock 55 shaft 198 by cam and follower connections from the main cam shaft 120 through connections which comprise one or more forwardly extending cam lever arms 206 on each of which is mounted a cam roller 208 arranged to ride against the peripheral surface of a knock-over bit forward and back motion cam 210. A heavy tension spring 212 acts to hold the cam lever 206 and roller 208 in engagement with its cooperating cam 210. In 60 the form of the invention shown, the knock-over bit assembly, including the knock-over bits 108 and knock-over bit frame 180 are arranged to be moved vertically by means of a mechanism which is adapted to provide alternatively for either a positive up and down motion or a downwardly 65 70 75

spring seated movement, as may be required for knitting of the different portions of the hosiery blank. As best shown in Fig. 11, tension springs 214 connected between the lower portions of the several frames 180, and anchorages on the sinker rail 112, tend to urge the frame 180 and knock-over bits 108 yieldably in an upward direction. The fulcrum pins 184 about which the knock-over bit bars swing forwardly and back are pivotally supported, and are held against upward movement against the action of the springs 214 above described, by means of two forwardly extending arms 216 which are mounted on a rock shaft 220 and are formed with semi-circular downwardly facing bearing slots to receive the fulcrum pins 184. The fulcrum pins are adjustably supported in the bearing slots by means of adjustable screw stops 218 threaded into the arms 216. Oscillatory movements are imparted to the rock shaft 220 by means of one or more cam levers 222, each extending downwardly from the shaft 220 and provided at its lower end with a roller 224 arranged to ride against a knock-over bit vertical motion cam 226 on the main cam shaft 120. A heavy tension spring 228 acting against the lower end of cam lever 222 tends to maintain the roller 224 in engagement with its cam.

In accordance with the invention means are provided which may be rendered operative at will to eliminate the downward spring seating of the knock-over bits under the influence of springs 214. The mechanism referred to comprises a rock shaft 230 mounted directly beneath the rock shaft 220 and to which are secured laterally extending arms 232 which are provided with adjustable stop screws 234 for engagement with the underside of the fulcrum pins 184. For imparting oscillatory movements to the rock shaft 230 there are provided one or more cam actuated levers 236 which have mounted thereon cam rollers 238 arranged to ride on a peripheral face of the operating cam 240. A heavy tension spring 242 connected to the lower end of each lever 236 tends to maintain the roller 238 in continuous engagement with the cooperating cam 240.

The manner in which the knock-over bits operate during the knitting will be described with specific reference to diagrammatic Figs. 64 to 71, inclusive. As above described the knock-over bits are spring seated forwardly and vertically and the pivotal support about which the knock-over bits turn is additionally adjustable to provide a positive support in the vertical plane in place of the spring seated support. The different positions assumed by the knock-over bits in a vertical plane are particularly shown in diagrammatic views, Figs. 64 to 71, inclusive. For the more efficient operation of the knock-over bits it is proposed in accordance with the present invention to provide a positive vertical support for the knock-over bits during the first portion of the knitting cycle up to and including the movement of the needles downwardly to the press. Particularly during the downward movement of the needles a positive control of the vertical position of the knock-over bits is of advantage to prevent the fabric from being forced downwardly by the frictional engagement of the loops about the needle shanks, and to make certain that these loops are moved over the beards of the needles while still closed. Fig. 64 specifically shows the knock-over bits in the partially retracted position which is maintained during the coulier and at a relatively low level. As the needles approach the pressing position as indi-

cated in Figs. 65 to 66 the knock-over bits are moved backwardly slightly to lead the backward movement of the needles. The position of the knock-over bits forward and back is such to avoid any possible strain on the sinker bars of previously knitted fabric which would interfere with the pressing movement of the needles. As the needles now move downwardly and rearwardly to the knock-over, the knock-over bits are moved to their extreme high position and at this time are spring seated, by virtue of a relative downward movement of the supporting screws 234 which close the semi-circular bearings for the knock-over bit frames. For the positions illustrated in Figs. 68, 69 and 70, the knock-over bits are spring seated in both the vertical and horizontal direction to resist the pulling of the bights of yarn as the needles carry the loops downwardly and backwardly between the knockover bits. The arrangement above described in which the knockover bits are positively seated in a vertical direction, particularly during the downward movement of the needles at the press, has the advantage of providing a positive and accurate control of the vertical position of the knock-over bits. In order that the position of the terminal loops of the previously formed fabric held on the shanks of the needles may be accurately and certainly determined, the subsequent spring seating of the knock-over bits when the needles are moved downwardly to the knock-over position has the specific advantage that the knocking over surfaces will act to maintain the knocked over loops under a proper tension without any necessity of adjustment of the knock-over bits in accordance with the length of loop being produced.

The operation of the knock-over bits during the narrowing operation is specifically illustrated in diagrammatic views Figs. 72 to 80, inclusive. As shown in Fig. 72 at the start of the narrowing operation, the knock-over bits are allowed to come forward. The nibs of the knock-over bits are at this time at a sufficiently low level so that they do not swallow the sinker bar of yarn so that the fabric tends to lie on the upper surface of the knock-over bits, including the nibs. As the narrowing points continue their downward movement to cover the needles to engage the loops to be extended lengthwise of the needle series, the knock-over bits are still maintained in this relatively forward position. As the narrowing points rise to lift the loops from the needles, the knock-over bits are similarly moved upwardly to assist in this operation. Thereafter during the lateral transfer movement of the narrowing points, the knocking over bits, as shown in Fig. 76, are depressed so that the narrowing points will more readily clear the tops of the knock-over bits. During the subsequent transfer operation, as shown in Figs. 77 to 79, inclusive, the knock-over bits are moved forwardly so that the knock-over bit nibs will engage and tension forwardly the fabric loops held on the narrowing points to receive the tips of the rising needles. As the narrowing points move upwardly clear of the knock-over bits and the needles rise between the sinkers, as shown in Fig. 80, the knock-over bits are again retracted to the position shown in Fig. 72. In the preferred form of the invention shown during this entire operation, the knock-over bits are positively supported in the vertical direction during the entire narrowing operation.

The narrowing machine, as generally shown in Figs. 5 and 6 of the drawings, comprises a sup-

porting rod 246 mounted on lever arms such as 247 at spaced intervals along the length of the machine for movement about a pivot shaft 248 (see Fig. 6) to move the narrowing machine toward and away from the needles. The usual narrowing points for performing fashioning operations are generally indicated at 249 (see Fig. 9) and are supported on a pair of left and right narrowing rods 250 slidably supported on depending brackets 251 secured to the supporting rod 246. The narrowing machine also provides support for a picot bar 252 for each knitting section. Each picot bar 252 is supported from a picot support shaft 253 rotatably supported in bearings formed on brackets 251. In accordance with the usual practice, the picot bars are arranged to be swung upwardly to inoperative position as shown for example in Figs. 2 and 9 and alternatively downwardly to operative position, as shown for example in Figs. 1 and 12 and in dot and dash lines in Fig. 2.

The narrowing machine is moved vertically by means of connections which may be of ordinary description, including one or more vertical links 254 (see Figs. 5 and 10) spaced along the length of the machine connected at the upper end to the narrowing machine frame and at the lower end to a cam lever 255 having a roller 256 adapted during normal knitting for engagement with a circular disc 257 and during the narrowing operation for engagement with a narrowing machine lift cam 258.

In the preferred form of the machine shown, a narrowing machine high lift mechanism is provided for raising the narrowing machine to an abnormally high position out of the path of movement of the welt mechanism during the operation of setting up and of turning the welt. The high lift mechanism comprises a swinging post 259 pivoted on a stud 260 in a lever 261 rigidly secured to a rock shaft 262. There is also secured to the rock shaft 262 an arm 263, a cam roller supporting arm 264 and a foot treadle lever 265. The post 259 is held yieldably in contact with a stop screw 266 on the arm 263 by means of a spring 267 so that upon clockwise movement of the shaft 262, the post will contact a notch in the end of roller lever 255 and will act upon further rotation of the shaft to lift the roller 256 off its cam disc 257. A tension spring 268 attached to the cam lever 264 tends to rotate the cam lever, the rock shaft 262, and associated parts in a counter-clockwise direction to the position shown in Fig. 5, in which the foot treadle lever 265 engages under the lower front rail 116 of the machine.

The cam lever 264 carries a stud 269 on which is slidably supported a cam roller 270. A shifting fork 271 loosely sleeved on a pattern rod 272 of the machine, and engaging a groove portion of the sleeve hub of the cam roller 270, acts to move the roller 270 into and out of engagement with high lift operating cam 273. The hub of the shifting fork 271 is abutted on one side by a collar 274 fixed on the pattern shift rod 272, and at its other side is acted upon by a spring 275 seated against a fixed collar 276 on the shaft. As best shown in Fig. 10, the sleeve hub of the shifting fork 271 is also provided with a downwardly extending lug 277 for alternative operation by a dog 278 pinned to a second pattern rod 279.

In the movement of the rock shaft 262 and associated parts, including the foot treadle lever 265, in a clockwise direction to an operating posi-

tion in which the post 259 engages the notch in the narrowing machine, lift cam lever 255 causes the foot treadle lever to ride beneath the notched lower end of a latch 280 supported on a pivot pin 281 on the lower front rail 116. An upwardly extending arm of the latch lever 280 carries a stud 282, which is arranged in the path of a dog 283 loosely sleeved on a pattern rod 284 being abutted on one side thereof by a collar 285 pinned to the pattern shift rod 284 and at its other side by a compression spring 286 seated against a collar 287 pinned to the shift rod 284.

The operation of the automatic narrowing machine high lift mechanism shown in Figs. 5 and 10 is briefly as follows: In the course preceding the setup, a chain rack causes shift rod 272 to move to the right to the position shown in Fig. 10, carrying with it the roller fork 271 and roller 270, which is thus placed in alignment with the high lift cam 273. The rise portion of lift cam 273 causes the rock shaft 262 and associated parts to be rocked in a clockwise direction from the position shown in Fig. 5 so that the post 259 is engaged with a notch in the narrowing machine lift cam lever 255, thereafter lifting these parts to the high position in which the foot treadle lever 255 will have moved beneath the notch end of latch 280, thus holding the parts in the abnormally high position. The narrowing machine remains in this high position until such times as the latch 280 is removed. The operation of latching the narrowing machine in the high position having been completed, the pattern rod 272 returns to its initial position, and roller 270 and shifter fork 271 also return to the position of Fig. 10 under the influence of spring 275 when relieved from the pressure of engagement with the high portion of high lift cam 273.

In accordance with the present invention, the pattern mechanism above described is employed to automatically move the narrowing machine again downwardly to its operating position when desired. To this end shift rod 279 (see Fig. 10) and dog 278 are caused to move to the right so that dog 278 engages lug 277 to move the shifter fork 271 and roller 270 again into alignment with the high lift cam 273 which operates as the roller engages the high portion of the cam to relieve the strain on latch 280. At the same time a shift rod 284 actuated by a button on the pattern chain is moved to the right, compressing a spring 286, (see Fig. 10) which acts when the weight upon the latch 280 is released to move the latch out of engagement with the foot treadle lever 255. As the high lift cam roller 270 now rides down the decline portion of the high lift cam 273 the rock shaft 262 is permitted to rotate in a counter-clockwise direction, first to lower the narrowing machine and its lift roller 256 to the operative position shown in Fig. 5, and thereafter to disengage the post 259 from the notch in the end of the cam lever 255.

The high lift mechanism is operated during the welt turning operation in a manner similar to that described in connection with the setting up operation except that in this instance the shifting of the shifter fork 271 and high lift cam roller 270 to the right to initiate the high lift cycle of operations above described is accomplished by a movement to the right of pattern control rod 279 and dog 278 which acts against the depending lug 277 of the shifter fork 271.

The picot bars 252 are normally shifted to the right by one needle index during the operation of lifting and transferring the loops of a regular picot course. The shift mechanism as shown in Figs. 6 and 12 of the drawings comprises a shift lever 290 which is loosely sleeved to turn on the narrowing machine shaft 246 and is provided with a downwardly extending arm arranged to engage with a collar 291 pinned to the picot support rod 253 and with an upwardly extending arm bifurcated to embrace an auxiliary narrowing machine shaft 292 rotatably supported in bearings on the narrowing machine frame. A cam collar 293 secured to the shaft 292 is arranged for engagement with a cam surface on the upper extension of lever 290 and acts to impart to the lever 290, collar 291 engaged thereby, and picot support rod 253 a shifting movement to the right when the shaft 292 is rocked. The picot support rod 253 is normally held in its position to the left by spring means of the usual type. Rocking movements are imparted to the auxiliary narrowing machine shaft 292 to effect the picot bar shifting movement above described by means of operating connections which include an upwardly extending lever arm 294 secured to the rock shaft 292, a link 295, a lever 296 loosely pivoted to turn on the narrowing machine pivot shaft 248 at the rear of the machine, a downward extending link 297 and a cam actuated lever 298 pivotally supported at 299 on a bracket 300 secured to the lower rear rail 114. The cam actuated lever 298 is provided at its forward end with a supporting stud 301 on which is slidably mounted a cam roller 302 for engagement with a cam 303 on the main cam shaft 120. A heavy tension spring 304 connected with the forward end of the cam actuated lever 298 tends normally to move the roller 302 into engagement with its actuating cam 303. A downwardly extending arm of the cam actuated lever 298 carries an adjustable stop screw 305 which engages against the lower rear rail 114 to limit the movement of the lever under the influence of its spring 304.

The mechanism for shifting the main cam shaft 120 axially to bring the narrowing machine cams including the picot shift cam 303 above described into operative position, is generally indicated in Figs. 1 and 8 of the drawings, and comprises a shift roller 306 which is arranged for engagement with a shift cam track 307 formed on adjacent faces of cam discs 308 rigidly secured to the cam shaft 120. Inasmuch as this mechanism for shifting the cam shaft 120 is well known in the art, and is controlled in the usual manner from the pattern chain of the machine, no further illustration thereof is believed necessary.

In accordance with the usual practice the operation of the machine is controlled from a pattern mechanism which takes the form of a pattern chain 309 which is supported along the length of the machine on sprocket rollers such as those indicated at 310 and 311 in Fig. 8 and at its left end rides around a driving sprocket drum 312 mounted on a supporting stud 313. Stepped racking movements are imparted to the chain in timed relation to the rotation of the main cam shaft 120 during the operation of knitting a stocking blank by cam actuated mechanism including a cam 314 and a cooperating bell crank cam follower lever 315 which is pivotally supported on a bracket 316 on the lower front rail 116 and carries a cam follower roller

317 on an upwardly extending arm lever. The other arm of the cam lever 315 is connected by a short link 318 with a pawl carrying arm 319 loosely supported to turn on the stud 313. A pawl 320 carried by the arm 319 engages with a ratchet wheel 322 formed as an integral unit with the sprocket drum 312.

In accordance with the present invention an improved system of automatic controls for the narrowing machine is provided for effecting movement of the narrowing machine to and from a high position out of the path of movement of the welt hooks for both the setting up and welt transfer operations and for controlling the operation of the picot lateral shift mechanism to a dummy picot motion for operatively engaging the welt wire with the welt wire takeup hooks and thereafter to form the picot in the usual manner. The movements imparted to the narrowing machine may be briefly outlined as follows: in accordance with the dictation of the pattern chain the narrowing machine is raised to its high inoperative position prior to the knitting of the welt setting up course. After a number of courses have been knitted, the narrowing machine is again automatically brought down to the operative position. At this time the picot bars with the welt wires mounted thereon are swung down manually into operative position preparatory for operatively connecting the welt wires with their takeups. Since a dummy movement only of the narrowing machine is required for carrying out this operation the picot bar lateral shift mechanism which would normally operate automatically is latched out of operation by automatic means. The picot lateral shift mechanism is again rendered operative by the release of the latch in the course of the welt wire laying-in operation. After one half the welt is knitted, the narrowing machine functions in the normal manner to form the picot. Again in accordance with the dictation of the pattern chain the narrowing machine is lifted to its high inoperative position for the welt loop transfer or topping operation, being thereafter again restored to its operative position in condition for the knitting of the usual narrowing courses of the leg.

In the illustrated machine the rightward shift of the pattern shift rod 272 in the idle course immediately preceding the welt setting up course performs a number of functions which include the shifting of a shifter fork 323 secured to the rod, and needle press cam roller 133 controlled thereby (see Figs. 3 and 10) onto setting up needle press cam 136; loading of a spring 335 shifter fork 334, and the main regulator cam roller 144 away from alignment with the main regulator cam 145 (see Figs. 6 and 10); the shifting of shifter fork 271 and narrowing machine high lift cam roller 270 (Figs. 10 and 5) into alignment with the high shift cam 273; and the shifting of the picot bar lateral shift cam roller 302 to an inoperative position in which it will not be aligned with its cam when the narrowing machine is rendered operative.

The connections for controlling the position of the picot lateral shift cam roller 302, as best shown in Figs. 6 and 12, comprises a roller shifter fork 324 loosely sleeved on the shift rod 272 abutting a fixed collar 325 on the shift rod. The shifter fork 324 and picot lateral shift roller 302 are moved to the right by action of the shift rod 272, and are latched in the shifted position by means of a latch 326 which engages behind an

abutment on the hub of the shifter fork 324. The latch 326 is supported on a stationary pivot pin 327 and has a pin and stop connection with a depending link 328 connected at its upper end with a forward extension 329 of one of the narrowing machine lift cam levers 255. A tension spring 330 connected between the free end of the latch 326 and a supporting pin 331 tends to hold the latch in latching position. A compression spring 332 interposed between the shifter fork hub and a collar 333 on the shift rod is loaded by the return movement of the shift rod 272 to the left and acts when the latch is released to return the pivot lateral shift cam roller 302 to its normal operating position. The release of the latch 326 and the return of the shifter fork 324 and pivot lateral shift cam roller 302 to the normal operating position is effected during the course of the laying in of the welt wires by a rocking movement of the narrowing machine lift cam levers 255 and of the arm 329 in a counterclockwise direction from the position shown in Fig. 6, which causes the latch 326 to be lifted out of engagement with the abutment on shifter fork 324.

The operating controls for the main stitch regulator of the machine include means operated from the pattern chain 309 of the machine for rendering the main regulator inoperative to control stitch length during the setting up of an initial course of welt fabric on the machine. The connections employed include a shifter fork 334 which is loosely sleeved on pattern shift rod 272 and is provided with an off set fork which engages the two faces of main stitch regulator roller 144. A compression spring 335 interposed between the sleeve hub of shifter fork 334 and a collar 336 fixed on the shift rod 272 tend to maintain the fork in a position to the right in engagement with a second collar 237 fixed to the shift rod 272.

The welt mechanism which forms specifically the subject matter of the present invention employs a welt bar with vertically arranged hooks which are constructed and operate in a manner which is substantially the same as the hooks illustrated and described in the U. S. patent to Lieberknecht 2,269,463, above referred to. In accordance with the disclosure of the Lieberknecht patent referred to, the welt hooks are disposed one for each alternate needle in cooperation with the needles to form an alternate needle set-up. To this end the welt hooks are moved downwardly to the beard sides of the needles during the formation of the setting up course, act as press elements to close the beards of alternate needles above the usual press level and thereby cause the loops to be cast off from alternate needles and thereafter, as the needles continue their downward movement, act to pick up the cast-off bars of yarn while held on the knock-over bits. For topping the initial course of loops of the welt fabric back onto the needles at the completion of the welt knitting, the welt hooks are again moved over the tops of needles to the beard sides thereof so that the loops of the initial welt course held on the hooks will be engaged by the rising needles to close the welt. In accordance with the disclosure of the Lieberknecht patent referred to, the welt bar and hooks mounted therein are maintained at all times in a vertical or substantially vertical position during the operations of setting up the initial course, of drawing off and folding the fabric, and of topping the loops of the initial course onto the needles to close the welt.

One of the welt hooks 350 employed with the present construction is illustrated on an enlarged scale in Fig. 51 of the drawings. As shown in this figure, the welt hook is provided with a bent shank portion and an elongated hook, the outer face of which is grooved to receive the beard during the alternate needle press operation and again during the upward movement of the needles for topping thereon the initial loops of the welt fabric. As best shown in Figs. 14-17, inclusive, the welt hooks 350, spaced to cooperate with alternate needles, are mounted in a slotted welt bar 352, being held rigidly in position by means of a cover plate 353.

Each welt bar 352 is rigidly supported upon two upwardly extending welt bar supporting arms 354 which are pivotally connected at 356 to the rearward ends of two horizontally disposed welt bar vertical motion levers 358 rigidly secured to a pivot shaft 360 extending along the length of the machine. As shown, for example, in Fig. 2 the vertical motion levers 358 pass beneath the welt cam shaft 362 which is mounted in the base of the machine and extends along the length thereof substantially above the main cam shaft 120 and beneath the work table 118. The rock shaft 360, the vertical motion arms 358 and welt bars supported thereby are urged in upward direction by means of one or more coiled tension springs 364 such as that shown in Figs. 2 and 9, which is connected at one end to a downwardly extending arm 366 rigidly secured to the rock shaft 360 and at its other end to a bracket 368 rigidly secured to the lower front rail 116.

Vertical movements are imparted to the welt hooks in timed relation to the operation of the needles in connection with the setting up operation and again during the welt closing or topping operation by means of one or more vertical motion cam levers 392 disposed along the length of the machine, such as that shown for example in Figs. 2 and 13, which is rigidly secured to rock shaft 360 and carries a roller 394 adapted for engagement selectively with any one of two alternative vertical motion setting up cams 396 and 398 and a vertical motion welt transfer cam 400 fixedly mounted on the welt cam shaft 362. With the arrangement shown the welt hooks are moved yieldably upwardly by means of the springs 364 and are moved positively downwardly by means of the cams 396, 398 and 400 during the performance of the respective setting up and transfer operations.

Movement of the shaft 360 and welt bar vertical motion support levers 358 upwardly under the influence of springs 364 is limited in an extreme upward position by the engagement of adjustable stop screws 370 screw threaded into the welt bar vertical motion levers 358 for engagement against the underside of a shaft 131 hereinafter to be described. At different stages of the welt knitting the welt bar vertical motion support arms 358 may be positively supported in either of two other alternative low positions by means of a downwardly extending detent arm 374 which is loosely sleeved on the shaft 131 and is formed with two notches adapted for alternative engagement with a horizontally disposed latch arm 376 which is rigidly secured to the rock shaft 360 to move about the shaft axis with the welt bar vertical motion support levers 358 (see Figs. 2 and 9). As best shown in Fig. 2, the position of the detent 374 is controlled automatically through mechanism which includes a rearwardly and downwardly extending cam lever 378 in-

tegrally connected with the detent 374. The cam lever 378 carries a stud 380 and a cam roller 382 shiftable thereon into engagement with either of two cams 384 and 386 on the main cam shaft 120 of the machine. Pattern actuated connections are provided for shifting the roller 382 including shifting fork 388 which engages a grooved hub of the cam roller 382 and is secured at its forward end to a pattern rod 390 extending along the base of the machine. As will hereinafter be further described in connection with the operation of the machine, the welt hooks are normally maintained in their extreme high position shown, for example, in Fig. 2 when the welt bar is inoperative. The adjustment of the stop screw 370 above described determines the height at which the welt hooks 350 pass over the heads of the needles during the early portion of the welt hook setting up operation. The remaining two positions include an extreme low position which is obtained when the latch 376 engages the lower or inner notch of the detent member 374 at which level the welt hooks are maintained with the lower ends thereof between adjacent sinkers during the knitting of an initial portion of the fabric, and an intermediate position which is obtained when the detent is moved clockwise a sufficient distance so that the latch 376 moves into engagement with the upper notch formed in the detent 374. The welt hooks are maintained in the intermediate position vertically during the knitting of a major portion of the welt fabric and particularly during the period when the welt wires are brought into active operation.

The mechanism provided in accordance with the present invention for controlling the forward and back movements of the welt hooks 350 and welt bar on the welt bar supporting arms 354 will be described as follows: The welt arms 354 and welt bar 352 associated with each knitting section are biased forwardly away from the needles by connections which include a cord 402 (see Figs. 2 and 22) which is connected at its free end to a forward extension 404 of each of the welt bar support arms 354 and is arranged to be wound on a drum 408 yieldably connected to turn with a welt bar take-up shaft 410 extending along the length of the machine. Each individual welt bar is tensioned forwardly in this manner by means of a yieldable drum connection with the welt bar take-up shaft 410. The shaft 410 is biased in a clockwise direction to exert a take-up strain on the several welt bars by means of a weight 412 (see Fig. 1) suspended on a cord 414 which passes upwardly around an idler roller 416 and thence to the take-up shaft 410.

The mechanism provided in accordance with the present invention for imparting forward and back movements to the supporting arms 354 and welt bar 352 mounted thereon comprises a rock shaft 420 which extends along the length of the machine directly to the rear of the machine table 118 and has mounted thereon for each knitting section two depending actuating levers 422, located at opposite ends of the section and having cam edges which engage with follower rollers 424 carried on the vertically disposed welt bar support arms 354. Rocking movements are imparted to the shaft 420 to rock the welt bar support levers 354 rearwardly and to carry the welt hooks to the beard side of the needles by means of cam and follower connections from the welt cam shaft 362 which comprise one or more depending cam levers 426 loosely sleeved to

turn on the rock shaft 420 and provided at its lower end with a roller 428 adapted for engagement with either of two welt set-up and welt transfer cams 430 and 432.

5 A yielding connection is provided between each cam lever 426 and the rock shaft 420 which causes the welt bar supporting arms and welt hooks to be moved rearwardly to the beard sides of the needles and to press. As best shown in Figs. 7 and 13 the hub of cam lever 426 is engaged on one side thereof by a collar 436 pinned to the shaft 420 and on the other side by the hub of a short lever arm 438 also pinned to the shaft 420. An offset outer end of the lever 438 carries an adjustable stop screw 440 which engages against the cam lever 426 to limit relative movement of these parts in one direction. A tension spring 442 connected between the cam lever 426 and the lever arm 438 acts normally to maintain the cam lever 426 solidly in engagement with the lever 438. The rock shaft 420 is biased in a counterclockwise direction as shown in Fig. 2 by means of the tension spring 444 which is connected to a downwardly extending arm 446 on the rock shaft 420.

In accordance with a feature of the invention a mechanism is provided for positively supporting the welt hooks in a position slightly away from the press edge during the alternate needle 30 pressing operation which takes place during the setting up of the initial welt course, and for thereafter positively moving the welt hooks forwardly over the tops of the needles after the pressing off of the alternate needles has been 35 accomplished. Positive assistance during the subsequent forward movement of the welt hooks is continued while the welt hooks move to engage thereon the cast-off bars of yarn. The auxiliary welt bar supporting and actuating mechanism 40 referred to comprises a rock shaft 450 (see Figs. 1, 2, 13, and 20) which extends along the length of the machine and is located adjacent to and rearwardly of the rock shaft 420 above described. Between each pair of knitting sections the shaft 450 has mounted thereon an upwardly extending lever arm 452 which carries at its upper end a supporting plate 454 which is arranged for a 45 rearward position of the arms 354 and welt bar 352 to engage with adjustable stop screws 456 carried on the welt bar supporting arms 354 (see Figs. 1, 2, and 13). Also rigidly secured to the rock shaft 450 are one or more welt hook 50 press control cam levers 458 such as that shown in Fig. 13 which is provided at its lower end with a roller 460 adapted for engagement with either of two operating cams 462 and 464 on the welt 55 cam shaft 362. The rock shaft is biased in the counterclockwise direction as viewed in Fig. 20 to maintain the roller 460 against its cam by 60 means of a tension spring 466 which acts against a downwardly extending lever 468 secured to the rock shaft 450. A rotational movement of the rock shaft in the counterclockwise direction is limited by means of a forwardly extending stop 65 arm 470 which carries a stop screw 471 adapted for engagement against the under side of the table 118.

The auxiliary welt bar supporting and actuating mechanism comprising the backing up plates 70 454 and arms 452 may also be employed to temporarily support any one of the welt bars 352 with its supporting arms 354 in an extreme rearward position in which underlying parts including the needles will be more readily accessible to the operator for adjustment and repair. For

this purpose each arm 452 has mounted thereon a latch arm 469 which is adapted when the welt bar has been pushed rearwardly to the desired out-of-the-way position to be swung upwardly by the operator into a horizontal position in which each latch 469 will engage a cooperating screw 456, to prevent any return forward movement of the welt bar under the influence of its tensioning cords.

In accordance with a feature of the invention the individual welt bars 352 are constructed and arranged to be readily detachable from their supporting lever arms 354 to permit easy access by the operator to underlying parts of the machine for repairs and adjustment. The locking mechanism provided is particularly constructed and arranged to enable the welt bar to be returned with a high degree of precision to the desired working position on the welt bar supporting arms 354 as best shown in Figs. 13 to 17, inclusive. As will be evident from the inspection of these figures, the welt bar 352 extends at each end substantially beyond the cover plate 353 thus providing at each end of the welt bar unit a vertically arranged flat surface, which is an extension of the slotted face of the welt bar and opposed undercut sloping surface 472 which provides a taper fit with a cooperating vertical wall 473 and an inwardly sloping wall 474 of a welt bar receiving socket formed on each of the welt bar supporting arms 354. A transverse pin 475 extending across a lower portion of the socket is arranged for engagement with an oversized square notch 476 cut in the underside of the welt bar 352 (see, for example, Figs. 14 to 16). The welt bar is locked in position in the socket at each end by means of a spring pressed tapered pin 477 which is arranged to fit into a correspondingly tapered hole 478 formed in each end of the welt bar 352. A coiled compression spring 479 coiled about the pin 477 and engaged at one end against the end well of the socket and at its upper end against a collar 480 fixed to the pin 477 tends to move the pin into locking engagement with the tapered hole 478 in the end of the welt bar. At its outer end the taper locking pin 477 is fitted with a cross pin 481 which is arranged for one angular position of the tapered pin to engage in an axially extending slot 482 in the welt bar supporting arm 354. When it is desired to remove the welt bar from the machine the taper locking pins 477 at each end are withdrawn and are rotated through 90 degrees so that the cross pins 481, which by this means are withdrawn from the slots 482, will be placed crosswise to the slots thus locating the locking pin 477 in a retracted position, this being the dot and dash position shown in Fig. 15. From an inspection of these figures, it will be readily seen that the tapered locking pin, when released by the alignment of cross pin 481 with its slot is spring pressed against the lower side of the tapered aperture 478 in the welt bar 352 to force the welt bar downwardly so that the flat vertical and cooperating tapered front and rear surfaces of the welt bar are firmly engaged by the cooperating flat and tapered surfaces of the socket to hold the welt bar very rigidly in the desired operating position. At the same time the expanding pressure of spring 479 tends to move the supporting arm 354 and socket longitudinally away from the end of the welt bar so that cross pin 475 is firmly engaged against the side of cooperating slot 476.

Further in accordance with the invention a

novel and improved means is provided for accurately aligning each individual welt bar with the needles and cooperating knitting instrumentalities of the associated knitting section for the performance of the setting up and welt topping operations. Improved means for aligning the individual welt bars herein disclosed consists of an upwardly extending fin 483 which is centrally mounted on the welt bar (see Figs. 1, 2, 9 and 13) and is arranged when the welt bar is moved forwardly into operating relation to the needles to engage between two stop screws 484 carried on the upwardly extending arms of a bracket 485 on the picot bar supporting shaft 253. This arrangement in which the welt bar is aligned with respect to the needles by a device centrally located of the welt bar has the advantage of greater simplicity. Difficulties arising from expansion or contraction of the welt bar or associated parts are eliminated, and any possible error which might result from such expansion or contraction of the welt bar with relation to the needle bar is minimized since in any event only a small portion of each bar could be affected.

The welt cam shaft 362 of the illustrated machine is driven intermittently from the main cam shaft 120 through a one revolution clutch, which is rendered operative during the setting up operation to rotate the welt cam shaft 362 through one revolution, and again during the welt transfer or topping operation to rotate the welt cam shaft through a second revolution. As hereinafter more fully set forth, the welt cam shaft is shogged to the left from a neutral position in order to bring the group of setting up cams into operation for the knitting of the setting up course, and is shogged to the right from the neutral position to bring the set of welt transfer cams into operation for the performance of the welt transfer or topping operation.

The mechanism for driving the welt cam shaft 362 from the main cam shaft 120 (see Figs. 8 and 18-20 inclusive) comprises a sprocket chain 486, which rides on a sprocket 487 pinned to the main cam shaft 120, and over a sprocket 488 loosely sleeved to turn on the welt cam shaft 362. The sleeve hub of the sprocket 488 is fixed against axial movement with the welt cam shaft 362 by the engagement of a follower carried on a key member forming part of a bracket 489 which is bolted to the underside of the work table 118 and adapted to engage in a groove 490 in the sleeve hub of the sprocket 488. One face of the hub portion of the sprocket 488 is formed as the one-toothed driving element 491 of a welt cam shaft driving clutch and is adapted for engagement with a corresponding recess formed in a driven clutch sleeve 492 which is keyed to turn with and to shift axially with rotation to the welt cam shaft 362.

The operation of the welt cam shaft driving clutch is controlled from the pattern mechanism of the machine through connections which include a clutch shifter yoke 494 which, as best shown in Fig. 19, comprises two arms extending upwardly from a sleeve hub carried on a transversely extending pivot shaft 496 which is supported on a depending bracket 498 bolted to the underside of the work table 118. The yoke 494 is provided with shoes 500 which ride in a peripheral groove 502 in the driven clutch sleeve 492. Two laterally extending lever arms 504, and 506 are mounted from the hub of the clutch shifter yoke 494 at one end thereof and a lever arm 507 extends from the midportion of the yoke hub.

A tension spring 508 connected between the arm 504 and a depending portion 510 of the bracket 498 tends to move the yoke 498 and driven clutch sleeve 492 out of engagement with the driving clutch 490. A stop screw 512 formed on a lug on arm 506 is arranged for engagement with a portion of the bracket 498 to limit movement of the shifter yoke and driven clutch element 492 under the influence of spring 508.

In order to return and to locate the welt cam shaft 362 in the same radial position after the completion of each successive revolution thereof a notch 514 cut into the peripheral surface of the driven clutch sleeve 492 is arranged to be engaged by a roller 516 carried by a detent arm 518 pivotally mounted at 520 on the bracket 498, the roller 516 and detent arm 518 being urged downwardly into engagement with the notch by means of a tension spring 522 attached to an extension of the detent arm 518. The sleeve clutch element 492 is positively shifted to the right to its inoperative position at the end of one revolution so that the detent roller 516 will be rendered operative to stop the welt cam shaft in the desired predetermined angular position by means of a clutch disengaging mechanism comprising a cam 524 which is secured to the right hand face of the driven clutch sleeve 492 and a cooperating roller 526 carried on the lever arm 507 attached to the yoke hub. The cam 524 acts as the driven clutch member 492 nears the completion of a revolution to engage with and to depress the roller 526 and arm 507 to move the driven clutch sleeve positively to its disconnected position as shown for example in Fig. 8.

The pattern control mechanism for shifting the welt cam shaft clutch to its driving position comprises a depending link 530 connected at its upper end to the yoke arm 506 and at its lower end to an arm 532 (see Figs. 8 and 18) secured to one end of rocker pin 534 sleeved in a bracket 536 on the lower front rail 116 of the machine. At its opposite end the rocker pin 534 has mounted thereon a pattern rod actuated lever comprising an upwardly extending arm 538 which engages against a collar 540 which is loosely mounted on a pattern rod 542 and is yieldably seated against a compression spring 544 and a supporting collar 546 pinned to the pattern rod 542. Rocking movement of the rocker pin 534 and associated parts in a clockwise direction from the position shown in Fig. 8 will cause the welt cam shaft clutch to be shifted to its engaging position. A detent consisting of a spring detent member 548 adapted for engagement with a notch in a cam rib 549 formed on the underside of the sleeve hub of arm 536 serves to support the rocker pin 534 and associated parts in the position which corresponds to the engaged position of the clutch.

The mechanism for shogging the welt cam shaft to the left to place the welt setting-up cams in operation and subsequently to the right to place the welt transfer cams in operation, as best shown in Figs. 1 and 8, comprises a pair of cam discs 550 and 552 which are spaced from one another on the welt cam shaft 362 and have formed therein opposed face cam tracks for engagement with a roller 554 carried on a welt cam shaft shifter lever 556 sleeved to turn on a pivot pin 558. A tension spring 560 tends to swing the shift lever 556 and roller 554 inwardly toward the axis of the welt cam shaft. The cam tracks included between the discs 550 and 552 comprise an outer neutral cam track generally indicated at 562 which is arranged to maintain the welt cam

shaft normally in its intermediate neutral position, a welt fabric setting-up cam track 564 which acts when the shift roller 554 is moved inwardly to shift the welt cam shaft to the left, and a welt transfer cam track 566 which acts when shift roller 554 is shifted still further inwardly, to shift the welt cam shaft 362 to the right from its intermediate neutral position. At the end of one revolution of the welt cam shaft for each of the setting-up and transfer operations the shift roller 554 and shift lever 556 are moved outwardly to their neutral position to realign the roller 554 with the neutral cam track and to cause the welt cam shaft to be returned to its intermediate position, by the engagement of a roller 568 with a cooperating face cam 570 carried on the cam disc 552.

Inward movement of the shifter cam lever 556 from the neutral to each of the welt setting-up and topping positions is controlled by means of a depending latch lever 572 which is secured to pivot pin 558 to turn with the shifter lever 556, (see Fig. 1). The latch lever 572 is formed at its lower end with three notches designated respectively as A, B, and C, which are alternatively engaged with a detent surface 574 formed in a horizontal arm of a laterally disposed detent lever 576 loosely mounted to turn on the pivot shaft 360. A tension spring 578 connected between the detent arm 576 and an abutment formed on the hub of the latch lever 572 tends to maintain the detent and latch in engagement with one another.

Operation of the detent lever 576 is controlled by means of connections which include a downwardly extending link 580 connected at its upper end to the detent lever 576 and at its lower end to one arm of a bell crank 582 (see Figs. 1 and 8) pivotally mounted on a bracket 584 on the lower front rail 116 of the machine. A second upwardly extending arm of the bell crank is arranged for engagement with a collar 586 pinned to a pattern rod 588.

In accordance with the present invention a booster mechanism is provided for engaging the welt cam shaft clutch and for shogging the welt cam shaft to each of its alternative operating positions, which comprises a booster cam on the main cam shaft 120 of the machine and pattern controlled follower connections therefrom. The operation of the booster mechanism is initiated by a racking of the pattern chain 309 of the machine which takes place in the next previous cycle of knitting movements of the machine. The cam actuated booster shift mechanism referred to, as best shown in Figs. 8 and 18, comprises a booster cam actuated pattern rod shifter lever 590 supported intermediate its length on a fixed pivot pin 592 and provided at its rear end with a stud 594 on which is carried roller 596 laterally shiftable into engagement with either of a setting-up booster shift cam 598 and a welt transfer booster shift cam 600 on the main cam shaft 120. At its forward end the shifter lever 590 is formed with a diagonally disposed cam track 602 in which is engaged the follower pin of a shifting collar 604 loosely mounted on the welt shogging mechanism shifter rod 588, and the follower pin of a shifting collar 606 fast on the welt cam shaft clutch actuating pattern rod 542. The shifter collar 604 is arranged to cooperate with a collar 608 pinned to the welt shogging cam shaft shifter rod 598, these collars being separated to introduce a lag into the movement of the cam shaft shogging device. A shifter fork 610 mounted on a pattern chain actuated pattern rod 612 and at

its upper end engaging the grooved hub of pattern rod booster shift roller 596 provides means controlled from the pattern mechanism of the machine for initiating the operations of engaging the welt cam shaft operating clutch and for shogging the welt cam shaft to one or the other of its operating positions.

The operation of the mechanism above described for shogging and for rotating the welt cam shaft through one revolution for each of the welt setting-up and welt topping operations will be briefly described as follows: During the cycle of knitting immediately preceding the setting-up course, an abutment on the pattern chain moves pattern rod 612 to the right (see Figs. 8 and 18), causing the pattern rod shifter cam roller 596 to be shifted onto the setting-up pattern rod shift cam 598. The rise portion of the cam 598 acts at the start of the coulier in the setting-up course to raise the pattern rod shifter cam lever 590 to an intermediate height. The follower pin collar 606 secured to the welt cam shaft clutch pattern shift rod 542 is moved immediately to the right loading spring 544 so that the one revolution clutch member 492 will engage with the driving clutch member 490 when the single tooth of the driving element comes into engagement with the corresponding recess in the driven clutch member. At the same time follower pin collar 604 on welt cam shaft shogging shift rod 588 is moved to the right (see Figs. 8 and 1), and after a time lag engages the collar 608 to move the welt cam shaft shogging shift rod to the right. This movement of the shift rod 588, acting through bell crank 582 and link 580, causes detent lever 576 to be depressed sufficiently so that detent 574 moves from notch A to notch B. Shift lever 556 and roller 554 now move inwardly into engagement with the setting-up cam track 564, thus causing the welt cam shaft 362 to be shogged leftwardly to the setting-up position.

At the end of one revolution of the cam shaft, the welt cam shaft is returned to its neutral position, and is disconnected from its driving mechanism in the following manner: The pattern cam shaft shifter lever 590 acting in response to movement of its roller onto a low portion of the shifter cam 598 causes the welt cam shaft shogging shift rod 588 and the welt cam shaft clutch actuating shifter pattern rod 542 to be returned leftwardly to the initial inoperative position. Pattern shift rod 612 again moves leftwardly to its initial inoperative position as the pattern chain is racked, causing the shifter roller 596 to be shifted to its inoperative position. Cam 570, acting on roller 568, causes the welt cam shaft shifter roller 554 and shifter lever 556 to return outwardly into engagement with the neutral cam track 562, so that the welt cam shaft 362 is returned to its neutral position. A cam 524 acts on roller 526 to rock clutch yoke 494 to disengage the clutch 492. Roller 516, engaging in a notch in clutch member 492, stops the welt cam shaft in the normal rest angular position shown, for example, in Figs. 1 and 8.

For the welt transfer operation, a bump on the pattern chain 309 is rendered operative by the racking of the chain in the course immediately preceding the welt transfer course to shift the pattern shift rod 612 to the right setting in motion the same sequence of operations as above described, except that the higher bump is employed, causing the booster control pattern shift rod 612 to be shifted further to the right, so that

shifter cam roller 596 is located in alignment with the welt transfer pattern rod shifter cam 600. Cam 600 acts to raise shifter lever 590 to a higher level at the beginning of the welt transfer course than was the case for the setting-up operation, with the result that welt cam shaft shogging shift rod 588 is moved further to the right, thus further depressing detent lever 576 so that detent 574 moves from notch A to notch C, and welt shogging cam roller 554 is permitted to move inwardly into engagement with the welt transfer cam track 566. The welt cam shaft 362 is now shogged to the right to the welt transfer position. At the end of one revolution of the welt cam shaft the parts are again returned to the normal neutral inoperative position in the manner described in connection with the setting up operation.

In accordance with the invention the illustrated machine is provided with an improved mechanism for effecting the folding and the taking up of the folded portion of the welt fabric. This mechanism comprises a welt wire support on the picot bar into which the welt wire can be laid prior to the time it is needed, a welt wire takeup device including welt wire engaging hooks, a pair of endless takeup chains by means of which the hooks and welt wire engaged thereby are drawn forwardly away from the needles and beneath the welt hooks, a pair of bridges on which the takeup hooks and welt wire are supported and guided during the movement away from the needles, takeup tensioning devices for biasing the takeup chains and hooks in a takeup direction, and mechanism acting automatically when rendered operative to return the takeup chains and welt wire engaging hooks to a reset operative position. In the illustrated form of the device, it is contemplated that nibbed knock-over bits, with which the machine is provided, will be utilized to clear the fabric from the needles as knitted and that the takeup action of the welt wire takeup may be suspended during the knitting of the lower leg and foot portion of the fabric as the welt wire takeup hooks move onto a downwardly inclined portion of their path approaching a fabric receiving hopper 616 located at the front of the machine (see Figs. 1, 2, 22 and 25).

The welt wire supports on which the welt wire associated with any knitting section is supported prior to the time it is required comprises two holders 614 attached to the front face of the picot bar 252 near the ends thereof. Each holder 614 is formed with a welt wire receiving throat portion 615 which for the operative position of the picot bar shown in Figs. 1, 6 and 12 extends forwardly and down. A spring clip (not shown) in the throat acts to hold a welt wire positioned therein yieldably in place.

As best shown in Figs. 1, 2, 22 and 25 of the drawings, there is provided with each section two rearwardly extending bridges 620, which are mounted on the work table 118 and provide a guide and support for the welt wire takeup hook assembly. Closely adjacent to the bridges there are two endless takeup chains 624 on which are mounted welt wire takeup hooks 626. The takeup chains 624 are arranged to ride around idler pulleys 628 pivotally mounted on brackets 632 fastened to the under sides of the bridges 620 at the ends adjacent the needles. The takeup chains extend forwardly closely parallel to the bridges 620 passing around idler rollers 634 loosely mounted to turn on a supporting shaft

636 and then downwardly and forwardly to driving and tensioning takeup sprockets 638 on a fabric takeup shaft 640. On their return path the take-up chains 624 are guided over idler rollers 642 and 644, thence returning to the idler pulley 628 above referred to. As best shown in Fig. 25 the rollers 642 are mounted on lever arms 645 pivotally supported on studs 646. A tension spring 648 attached to a downwardly extending hook 650 on each lever arm 645 and at its other end to the underside of the machine table 112, acts to bias each roller 642 against the chain 624 to eliminate any slack therefrom. At each section of the machine there is provided also a fabric guide 621 in the form of a highly polished metal strip which is supported by and fills the space between the bridges 620 and take-up chains 624 and which extends from a point closely adjacent to the knitting point forwardly across the work table 112, over the shaft 636 hereinafter described, and thence in a generally downward direction over the fabric take-up shaft 640 as indicated at 622. At its lower end the fabric guide 621, 622 terminates in the hopper 616.

Two crossbars 652 and 653 secured to the take-up chains 624 forwardly of the welt wire engaging hooks 626 with their end portions engaging the bridges 620, serve to maintain the hooks 626 in alignment and at the desired level.

A takeup tensioning strain is imparted to the several welt bar takeup chains 624 by means of a conventional weight not shown, and cord 654 which is attached to a pulley 656 secured to the right hand end of the fabric takeup shaft 640, see Figs. 22 and 25. In order to maintain a light and sensitive takeup tension through the individual pairs of takeup chains and hooks to the fabrics being knitted on the several knitting sections, a yieldable connection is provided between each driving sprocket 638 and the takeup shaft 640 on which it is supported. As best shown in Figs. 22-24, inclusive, each sprocket 638 is provided with a sleeve hub which is free to turn on a roller bearing provided on a sleeve element 658 fast on the fabric takeup shaft 640. The sprocket 638 is permitted a limited movement only with respect to the sleeve bearing member 658 by means of a lug 660 fast to the sleeve member and arranged to engage in a radial slot 662 in the sleeve hub of the sprocket 638. A coiled tension spring 654 secured at one end to a collar 666 on the shaft 640 and at its other end to the sleeve hub of the sprocket 638 tends normally to rotate the sprocket and takeup chain 624 engaging therewith to tension these parts with relation to the takeup shaft 640 in a takeup direction away from the needles. A yieldable takeup connection, such as that above described, is provided between each of the driving sprockets 638 and the fabric takeup shaft 640.

In accordance with the invention the machine is provided with a mechanism which is rendered operative by a dummy downward movement of the narrowing machine and picot bar to locate a welt wire supported on the picot bar in position to be engaged by the welt wire takeup hooks and for thereafter tripping the welt wire takeup into active operation to engage the welt wires therein and to take up the welt fabric. The welt wire takeup chains 624 and hooks 626 are supported in a pre-set position against the tensioning strain of the weighted fabric takeup shaft 640 by means of latches 670 which are carried on pivot pins 672 on the inner sides of the respective tracks 620

and are provided with abutments 674 which engage behind the more rearwardly disposed cross bar 652. The latches are normally maintained in the raised position shown for example in Fig. 5 by means of a tension spring 676 attached to a downward extension 678 of the latch. A tail 680 of the latch is arranged to engage against a portion of a supporting bracket 682 to limit the upward movement of the latch in a clockwise direction. Each latch is provided toward its rear end with an upwardly offset portion 684 which is arranged to be engaged by a welt wire mounted in the holder on the picot bar during the dummy downward movement of the narrowing machine 15 to cause the latch to be tripped downwardly to release the takeup chains 624 and hooks 626 therefrom as the welt wire is moved into its engaging position with the hooks. With respect to this operation particularly shown in Figs. 26 and 20 after the hooks have engaged the welt wires the subsequent upward movement of the narrowing machine and picot bars with the holders causes the welt wires to be forced out of the holders, thus completing the operation of transferring the welt wires from the holders to the hooks and into active operation.

Further in accordance with the invention, a mechanism is provided which acts automatically when the takeup movement of the welt wire takeup chains and hooks 626 are brought then to the dot-and-dash position of Fig. 25 to arrest further takeup action of the hooks and to automatically return them in a reverse direction to the pre-set position of Fig. 26 above described. The 35 reset mechanism (see Figs. 21, 22 and 25) comprises a reset pawl 686 and a cooperating ratchet 688 secured to the fabric takeup shaft 640. The pawl 686 is mounted on the free arm of a continuously reciprocated cam lever 690 which is 40 loosely supported to turn on shaft 131 and is provided at its rearward end with a cam roller 692 for engagement with a cam on the main cam shaft 120 of the machine. A tension spring 694 attached at one end to a downward extension of 45 the reset latch 686 and at its other end to the cam lever tends to move the latch into engagement with the ratchet. A locking pawl 696, see Fig. 21, is mounted in substantially parallel relation to the reset pawl to turn on a stationary bracket 698 and is arranged to be held yieldably 50 in engagement with the ratchet 688 by means of a tension spring 700. The reset latch 686 and locking pawl 696 are normally held in inoperative position out of engagement with the ratchet 55 688 against the pressure of their respective springs by means of a shield lever 704 which is pivotally mounted on the supporting shaft 636 and is bifurcated at its lower end to provide two shield elements, one at each side of the ratchet 638 for engagement beneath the edges of respective 60 reset and locking pawls, see Figs. 21 and 25. The shield lever 704 also has formed as integral parts thereof a latch arm 708 and a detent arm 710. A tension spring 712 connected at one end 65 to the arm 708 and at its other end to a fixed portion of the machine tends to swing the shield lever and associated parts in a clockwise direction to the position shown in Fig. 25 in which the reset pawl 686 and locking pawl 696 are held out of operation, movement of the shield arm in the clockwise direction being limited by engagement of an adjustable stop screw 714 on the arm with an abutment 716 on the machine frame. At the start of the operation of knitting a stocking, the shield lever 704 will be located in the position

shown in Fig. 25 in which the reset pawl 686 and locking pawl 696 are out of operation. When the knitting has progressed to a point at which the welt wire takeup hooks 626 reach the dot-and-dash position shown in Fig. 25, the leading cross bar 653 is brought into engagement with the latch arm 708 of the shield lever 704 and acts to move the shield lever in a counterclockwise direction so that the continuously reciprocating reset pawl 686 and the locking pawl 696 are brought into engagement with the ratchet 688 to impart a step-by-step resetting movement to welt bar hooks 626 and chain 624. The shield pawl 704 is latched in this inoperative position during the entire time that the welt wire hooks and chains are being reset, by means of a latch lever 718 which is supported on a fixed pivot 720 and has a hooked outer end for engagement with the detent arm 710 of the shield lever 704, a tension spring 722 connected between the latch lever 718 and a fixed point on the machine tends to move the latch into engagement with the detent arm 710. A second arm 724 of the latch lever 718 is arranged to be engaged by a cross bar 726 connected across the return portions of the chains 624 when the chains 624 and hooks 626 have been moved in the reverse direction to their starting position to trip the latch lever 718 and thus to permit the shield lever 704 to move clockwise under the influence of the spring 712 to again render the reset pawl 686 and locking pawl 696 inoperative.

In accordance with another feature of the invention the present machine is provided with a mechanism for severing the clamped starting end of the welt thread shortly after the knitting of the welt has started. The thread cutter provided in accordance with the invention comprises a pivoted cutter arm 730 which is supported to turn on a pivot pin 732 on the left hand rail 620 associated with each knitting section. A torsion spring 734 coiled about the pivot pin 732 and engaged at one end with the cutter lever and at its other end to a fixed portion of the machine tends to swing the cutter blade in a counterclockwise direction to the position shown, for example, in Fig. 28 in which the blade acts against an anvil surface 736 to sever a thread leading from the supply to the first course knitting. In order that the thread may be accurately located with relation to the cutting surfaces, an upwardly projecting thread guiding member 738 is mounted on the left hand bridge at the rearward end thereof to engage with and position the yarn which extends rearwardly from the usual clamp 739 to the yarn carrier (see Fig. 22). The pivoted cutter arm 730 is supported in a raised position against the pressure of its spring 734 by means of a latch arm 740 mounted on a pivot pin 742 for engagement behind a notch 744 in the hub of the cutter arm 730 and held in its latching position by means of a torsion spring 746. Controlling these parts there is provided integral with the cutter arm a reset arm 748, which is arranged to be engaged by a laterally extending lug 750 formed integrally with the hook 624 associated with each knitting section. The cutter latch arm 740 is similarly provided with an upwardly extending trip arm 752 which is arranged in the path of movement of the more rearwardly disposed cross bar 652.

The operation of the cutter is controlled by a rearward movement of the welt wire takeup chains 624 and hooks 626 from the reset position which causes the more rearwardly disposed cross

bar 652 to engage with the trip arm 752 to release the latch 740, causing the cutter to descend to sever the thread. This is the position of the parts shown in Fig. 28. This added increment of rearward movement of the chains 624 and hooks 626 to trip the cutter is effected by the action of the welt wire takeup tension relieving mechanism of the machine and takes place during the knitting of the setting up course. The return movement of the chains 624 and welt wire hooks 626 in a forward direction when tripped into active operation to engage and tension the welt wire as shown in Fig. 30 causes the laterally extending lug 750 on the adjacent hook 626 to engage the reset arm 748 associated with the cutter arm 730 to reset the cutter arm in its initial position in which it is again held by the latch 740. It will be understood that individual cutters are provided for each knitting section of the machine, and that the welt wire take-up tension relieving mechanism operates as above described to cause all of the cutters along the length of the machine to simultaneously cut the clamped ends of welt thread for the several knitting sections.

The rearward movement of the welt wire takeup chains 624 and hooks 626 above described for actuating the cutter is effected by means of the same mechanism which is employed to relieve the tension on the knitted fabric. This mechanism, as best shown in Figs. 7 and 12 of the drawings, comprises a tension relieving pawl 758 and ratchet 760 on the fabric take-up shaft 640. The take-up pawl 758 is pivotally supported on one arm of a cam actuated lever 762 which is loosely supported to turn on the shaft 131. A tension spring 764 attached to the pawl 758 tends to move the pawl toward the ratchet and against an adjustable stop screw 766 on the cam lever arm 762. A downward extension of the cam lever 762 carries a roller stud 768 on which is shiftably supported a cam roller 770 which is shiftable rightwardly into engagement with a thread cutter trip cam 772 and upon movement still further to the right into engagement with a tension release cam 774 for relieving the tension during the transfer operation. There is also provided on the main cam shaft a tension release cam 776 which is rendered operative by the shogging of the main cam shaft 120 to its narrowing position to relieve the take-up tension during a narrowing operation. The cam roller 770 is shifted into position for relieving the tension during the toppling operation and for rendering the thread cutter trip mechanism operative by pattern control means which includes a pattern chain actuated shift rod 778 and a shifter fork 779 engaging with a grooved sleeve hub of the cam roller 770. As shown in Fig. 7, the cam lever 762 is also provided with a laterally extending arm 780 which carries a stop screw 782 adapted for engagement against the welt cam shaft 362 to limit the movement of the cam lever 762 and associated parts in a clockwise direction as best shown in Fig. 7.

The operation of the machine for the knitting of the welt portion of a full-fashioned hosiery blank, including the setting up, drawing off, folding, and closing of the welt will be described as follows: The conditioning of the machine for the starting of the welt requires two idle courses prior to the knitting of the setting up course. In the first idle course in which the coulier is from left to right the racking of the pattern chain, which takes place in the knitting cycle at from 240° to 300° of rotation of the main cam shaft from zero position and shortly after the dividers come for-

ward, causes shift rod 157 to move to the right (see Figs. 10 and 5) loading spring 158, shifter fork 156 and special regulator cam roller 153 toward alignment with the special setting up regulator cam 152. The shift rod 157 is held in its shifted position for two courses.

In the second idle course in which the coulier is from right to left the following operations take place: The special regulator cam roller 153 urged by its spring 158 comes opposite a low portion of the special regulator cam 152 and moves into alignment therewith. Shifter rod 272 shifts to the right so that shifter fork 323 and needle press cam roller 133 move to the right (see Figs. 10 and 3) onto the setting-up needle press cam 136; spring 335 loads shifter fork 334, and main regulator cam roller 144 (see Figs. 10 and 6) for movement to the right out of alignment with the main regulator cam 145; shifter fork 271 and narrowing machine high lift cam roller 270 (Figs. 10 and 5) shift into alignment with high lift cam 273; and shifter fork 324 and picot bar lateral shift cam roller 302 move to the right to inoperative position. Shifter rod 612 shifts to the right to align booster roller 596 with setting up booster cam 598 (see Figs. 8 and 18).

Pattern shift rod 718 (see Figs. 7 and 12) moves to the right, causing shifter fork 719 and tension release cam roller 770 to be moved into alignment with the yarn cutter trip cam 772.

The machine stops and the welt thread carrier is connected to its friction driver in the usual manner.

In the setting up course the following operations take place: The booster cam acts immediately to rock cam lever 598 to an intermediate position; shift rod 542 is moved to the right, loading spring 544 so that the one revolution clutch member 492 is brought into engagement with the driving clutch member 490; shift rod 583 after a short time lag is similarly moved to the right causing latch lever 573 (see Fig. 1) to be moved downwardly into engagement with notch B of the detent 572 so that shifter roller 552 is moved inwardly to the setting up position to shift the welt cam shaft 362 leftwardly to the setting-up position.

Since both the main regulator roller 144 and the special setting-up regulator roller 153 are aligned with the respective cams (see Fig. 10) and spring 335 associated with the main regulator roller 144 is loaded by the previous movement of shift rod 272 to the right, the main regulator moves to inoperative position and special regulator roller 153 takes over control of stitch regulation in the setting-up course.

Pattern chain 309 racks, leaving shift rod 272 free to return to its inoperative position when permitted by the action of the roller.

The press cam roller 133 remains in its shifted position until the load is removed from needle press roller 133 by the taking over of the main regulator in the next course.

Pattern shift rod 94 (see Figs. 3 and 10) shifts to the right so that shifter fork 95 and needle vertical motion cam roller 92 move into alignment with the special setting-up vertical motion needle cam 91. This shifting takes place at approximately 270° of rotation of the cam shaft in the setting-up course.

After the special regulator has acted to locate the needles for the sinker yarn measuring operation and as the needles are moved to the setting-up press position, a slightly higher portion of the special regulator cam rocks the regu-

lator shaft sufficiently to relieve the load on the main regulator cam roller 144 which is permitted to ride up a small cam incline and to shift leftwardly to its normal operating position under the pressure of the usual return spring for shift rod 272. Immediately thereafter special regulator roller 153 is permitted to return leftwardly to its normal inoperative position under the influence of the usual return spring for shift rod 157.

The operation of the knitting instrumentalities and of the welt hooks cooperating therewith during the knitting of the setting-up course will be described in connection with the series of diagrammatic views, Figs. 39 to 53, inclusive, as follows: Fig. 39 shows the relative positions of needles, sinkers and knock-over bits in the normal starting position for zero degrees of rotation of the main cam shaft. The needles are standing in their highest position and the sinkers are retracted preceding the traverse of the yarn carrier and sinker slurcock cam from left to right. The relative positions of the cooperating knitting and welt instrumentalities in each of the figures referred to has been plotted for successive angular positions of the cam shaft in terms of degrees of movement of the cam shaft from the zero position. In this connection it is noted while the welt cam shaft rotates in a 1 to 1 ratio with the main cam shaft, the welt cam shaft is not clutched to turn therewith until after the cam shaft is rotated through 60°. The rotation of the welt cam shaft will then continue during the first portion of the next knitting cycle.

Starting from the zero position in Fig. 39, the yarn feeding and yarn sinking operations take place, including the coulier stroke of the welt yarn carrier and the sinker slurcock cam from left to right and the subsequent advance of the dividers to reform the loops so that the yarn kinks are reformed against the shanks of all the needles, this being the position of Fig. 43. During this period at between 77 and 100° of rotation of the main cam shaft the welt cam shaft is shifted to the left from the position shown in Fig. 13 to align the set-up cam 430 with roller 428 of the horizontal motion mechanism and to align cams 396 and 398 with the roller 394 of the vertical motion mechanism and to align press cam 464 with roller 450 of the welt bar steady-ing mechanism.

Between 145° and 200° of rotation of the main cam shaft the welt hooks will be moved in an arc from the idle position shown, for example, in Figs. 1 and 2 to the position shown in Fig. 40 in which they are positioned directly over the needles. During subsequent operation of the machine the welt hooks continue to move rearwardly and then downwardly to the beard side of the needles, the position of the several cooperating instrumentalities at 251° of rotation of the main cam shaft being indicated in Fig. 41. As shown in Fig. 42 at 260° of rotation of the main cam shaft, both welt hooks and needles are moving downwardly toward the tops of the sinkers and dividers. Immediately after the dividing sinkers are fully advanced, the welt hooks move below the top level of the sinkers and are held by these parts in alignment with alternate needles.

At 271° of rotation of the main cam shaft (Fig. 43) the special needle press cam 133 (see Figs. 3 and 10) takes over the control of the needles 75 allowing the special setting-up tight stitch reg-

ulator roller 153 to return to its idle position and the main regulator cam roller 144 to again become aligned with its cam 145. At this time the welt hook bar is steadied and made more rigid by the backing up plates 454 which contact the screws 455 of welt bar arms 354. The welt hook horizontal motion cam 436 is of constant radius from about 273° and the welt press backing up cam is similarly radial from 271° to 310° so that the welt hooks move vertically downwardly with screws 455 in contact with backing up plates 454. In the position of Fig. 45 at 281° of rotation the high point of needle press cam 136 is directly under its roller 133, thereby causing alternate needles of the needle series to press the beards against the welt hooks so that continued downward movement of the needles causes these intermediate needles to shed the loops held thereon. In Fig. 46 at 294° of rotation the welt hooks are continuing their downward movement, the sinkers are being retracted into the sinker head as in normal knitting, and the needles are moving downwardly and away from the press position under the influence of the setting-up needle press cam 136. The welt bar backing up plates 454 continue to guide the movement of the welt hooks which move slightly forwardly following the outward movement of the needles. As shown in Fig. 47 at 310° of rotation, the alternate bars of yarn cast off as above set forth are stretched across the noses of the still retracting sinkers. As shown in Fig. 48 at 312° the continued forward and downward movement of the welt hooks will have caused the bars of yarn to leave the noses of the sinkers at the same time that the front portions of the welt hooks contact and push these bars in a forward direction. The welt hooks maintain a slight tension on the bars of yarn during the period while the welt hooks cross the line of the heads of the needles. As shown in Figs. 49 and 50 at 320° and 323° respectively, the welt hooks are urged to the backsides of the needles by the rapid movement of the needles rearwardly toward the press at the knockover level effected by the needle press cam 136 which has a very sharp rise immediately after 310° in order to position the hooks for a dip to engage the pressed off bars of yarn. As shown in Figs. 51 and 52 at 328° and 335° respectively, the vertical position of the welt hooks remains stabilized and the welt hooks move forwardly away from the needles under the influence of the usual welt hook take-up tensioning device. In order to maintain a close margin of clearance between the bottom of the welt hooks and the tops of the needles for the positions shown in Figs. 47 and 48 the welt bar setting-up vertical motion cam 396 has an adjustable segment 318 as shown in Figs. 13 and 32.

It will be noted that the rise portion of the welt bar backing up plate cam 432 is much steeper than the corresponding drop portion of the in and out motion welt cam 436 so that the yieldable connection particularly shown in Fig. 7 between the cam follower lever 426 and the welt bar supporting rock shaft 429 becomes operative to support the welt hooks under a relatively strong spring pressure against the backing up plates 454.

As shown in Figs. 50 to 52, inclusive, from 323° onward until the welt hooks are subsequently raised slightly for the forming of a fold of welt fabric by the welt wire, the welt hooks are located vertically with the lower end of the hook projecting about $\frac{1}{8}$ of an inch below the top

surface of the knockover bits. Movement of the welt hooks to the extreme low position under the influence of the vertical motion setting-up cam 396 permits detent lever 374 (see Fig. 2) to move over latch lever 376, which is secured to welt hook vertical motion rock shaft 398 so that the latch engages the lower step of the notched end surface of detent 374.

After the knitting of approximately two inches of welt fabric the position of the welt hooks is adjusted vertically partly in order to provide space for the movement of the welt wires therebeneath, and partly to compensate for the downward increment of the movement of the welt hooks swinging on their arms 354 about the pivotal connection with supporting arms 358. To this end shift rod 390 (see Figs. 2 and 9) moves to the right sufficiently to align roller 382 on detent operating roller 382 to the right into alignment with cam 384 which acts to rock detent 374 sufficiently so that latch lever 376 rides onto the upper or outer step of the notched lower end of detent 374. Also preparatory to the laying in of the welt wire, the narrowing machine is moved automatically down from its high inoperative position. Shift rod 279 (see Figs. 5 and 10) and dog 278 are moved to the right in response to the dictation of the pattern chain moving shifter fork 271 and high lift cam roller 276 to the right into alignment with the high lift cam 273. At the same time the shift rod 284 also controlled from the pattern chain is moved to the right loading spring 286 which acts when the weight upon the latch 280 is released to move the latch out of alignment with the foot treadle lever 265. The operator now turns the several picot bars 252 downwardly to the operative positions so that the welt wires held in the holders on the picot bars are in position for the welt wire laying operation.

The machine is preferably conditioned for operation at a reduced speed.

The welt wire laying operation is now initiated by the usual pattern chain operated narrowing control (not shown) which operates to shift the main cam shaft rightwardly to the usual narrowing position. Since the picot lateral shift mechanism is latched out of operation as above described, a dummy narrowing operation only is performed by means of which the welt wires and their holders are brought downwardly, as shown in Figs. 28 and 30, to position the welt wires in the path of movement of the welt wire takeup hooks 626 and to trip the hooks into engagement therewith. Latch arms 684 which are pressed downwardly by the welt wires serve to release and to cause the welt wire takeup hooks 626 to engage with and to tension the welt wires against the fabric.

As shown in Figs. 6 and 12, the extreme downward movement of the narrowing machine frame during the dummy narrowing motion is accompanied by a rocking movement of the narrowing machine vertical motion cam lever 255 and a forward extension thereof of 328 which disengages the picot lateral shift motion latch 326, thus permitting the picot lateral shift motion roller 382 to be re-established in its operative position.

The forward movement of the takeup chains 624 and welt wire hooks 626 to engage with and tension the welt wire (see Figs. 28 to 30, inclusive) causes the laterally extending lug 750 on the adjacent hook 626 associated with the cut-

ter arm 730 to reset the cutter arm in its initial position in which it is again held by a latch 740.

When one half the welt has been knitted, the narrowing machine is rendered operative in the normal manner in response to a dictation of the pattern chain to form the picot.

The transfer of the initial setting-up course back to the needles to close the welt is entirely automatic and is controlled from the pattern chain of the machine. The machine is conditioned for slow speed operation. In the course immediately preceding the transfer, a button on the pattern chain acts to shift pattern shift rod 279 and dog 278 shifting fork 271 and narrowing machine high lift cam roller 270 to the right into alignment with the narrowing machine high lift cam 273. The narrowing machine is thereupon lifted and is latched in its high position to avoid possible interference with the welt hooks during transfer operation (see Fig. 10). Shift rod 778 (see Figs. 7 and 12), shifter fork 779, and tension release cam roller 770 are shifted to their extreme position to the right into alignment with fabric tension release cam 774. The contour of tension release cam 774 is such that the tension release lever 162 and pawl 158 acting on ratchet 160 release the tension on the fabric slightly in advance of the time when the welt hooks start their rearward movement over and to the beard sides of the needles. The tension is relieved by the action of cam 774 for a limited time only in order to assist the welt hooks during their rearward movement. Shift rod 612 is shifted to the right a sufficient distance to bring the booster cam roller 596 into alignment with the transfer booster cam 600.

At the beginning of the welt transfer course the booster transfer cam 600 acts to raise the booster cam lever 590 to its extreme high position. The welt clutch shift rod 542 is shifted to the right, thus loading spring 544 so that the one position welt cam shaft clutch 492 is engaged with the driven clutch 488 to drive the welt cam shaft 362 (see Figs. 8 and 18). After a short time lag, welt cam shaft shogging shift rod 588 is shifted to its extreme position to the right (see Figs. 8 and 1), thus rocking the latch lever 576 into engagement with the most downwardly disposed step surface C of detent lever 572 so that the welt cam shift roller 554 is moved inwardly a maximum distance into engagement with the welt cam shaft transfer shift cam track to shift the welt cam shaft 362 rightwardly to its transfer position.

In order to avoid interference with the operation of the welt cams during the transfer, it is necessary to again disengage the detent 374. To this end pattern shift rod 390 is shifted to the right when the chain racks in the transfer course, thus shifting shifter fork 388 and roller 382 to a position to the extreme right for engagement with cam 386. Immediately thereafter and before the welt hooks start their final upward movement, detent 374 is moved clockwise to the extreme position shown in Fig. 2. Rocking movement of the welt vertical motion pivot shaft 360 and latch lever 376 in a clockwise direction as the welt hooks move to their high position causes the latching lever 376 to engage against the side of detent 374 which is the final rest position shown in Fig. 2.

The operation of the knitting instrumentabilities and of the welt hooks cooperating therewith during the knitting of the welt transfer course will be described in connection with the

series of diagrammatic views, Figs. 55 to 63, inclusive, as follows. In this operation the welt cam shaft 362 is shifted rightwardly between 116° and 149° of rotation of the main cam shaft 5 so that up and down motion cam 400 is aligned with roller 394 and the in and out motion welt transfer cam 432 is aligned with roller 426.

At about 169° of rotation of the main cam shaft the forward and back welt transfer roller 428 contacts its cam and the felt hooks move slowly toward the needles. The up and down position of the welt hooks is determined by detent 374 (see Fig. 2) until approximately 307° of rotation of the main cam shaft when the vertical motion roller 394 comes into engagement with its cam 400. As shown in Fig. 55, at 307° of rotation of the cam shaft, the knitting needles are approaching a knockover position prior to the knocking over of newly formed loops. The sinkers are being retracted. The welt hooks are moving rearwardly toward the press, at a relatively low level at which they will still clear the tops of the needles so that the fabric loops held on the welt hooks will go under the noses of the sinkers. As shown in Fig. 56 at 318° of rotation, the needles are continuing their downward and rearward movement at the knockover, the sinkers are still further retracted, and the welt hooks are firmly backed against the press edge under the yielding spring pressure provided by the yieldable connection between the in and out motion cam lever 426 and the welt in and out rock shaft 420. The welt hooks are located vertically in a relatively depressed position in which the initial course of loops are located as low as possible on the tops of the knockover bits in position to receive upwardly moving needles. As shown in Fig. 57 at 323° of rotation, the upper end or head of the needle has engaged the grooved front surface of the welt hook at its lower end. The needle, riding in the grooved front face of the welt hook, moves upwardly through the spread loop. As shown in Figs. 58 and 59, the needles continue to rise while the welt hooks move still lower between the knockover bits to further facilitate the transfer of the loops onto the needles. As shown in Fig. 60 the welt hooks have moved to their extreme low positions in order to shed the initial course of loops from the hooks. Each alternate needle now has two bights of yarn on its shank below the tip of the beard. The intermediate needles, not specifically illustrated in the diagrammatic views, have each only the one newly formed loop thereon. Figs. 61 to 63, inclusive, show the final stage of the welt transfer in which the welt hooks, following the upward movement of the needles, rise to the beard side thereof and then move forwardly over the tops of the needles to inoperative positions. As specifically illustrated in Fig. 62, the welt hooks, when moved upwardly clear of the press edge, will be snapped rearwardly away from the needle beards under the influence of the tension provided in the yieldable connection above referred to, between the welt forward and back cam lever 426 and the welt forward and back motion rock shaft 420. This action has been found to be of considerable value to prevent possible inadvertent contact of the hooks with the needle beards, with possible resulting damage.

In accordance with the preferred form of the invention, the take-up of the fabric is continued under the tension provided by take-up roller 640 until the welt hooks reach the dot-and-dash position shown in Fig. 25, at which time the more

forwardly disposed crossbar 653 engages with and trips latch arm 708 of shield lever 704 to bring the reset pawl 686 and locking pawl 696 into engagement with the ratchet 688, so that a step by step resetting movement is thereafter imparted to the welt bar hooks 626 and chain 624. At the completion of the resetting operation, the crossbar 726, connected across the return portions of the chains 624, engages latch lever 718, which in turn permits shield lever 704 to move reset pawl 686 and locking pawl 696 out of operation.

Further in accordance with the invention it is contemplated that when the welt wire take-up provided by welt wire take-up hooks 626 is discontinued for the continued leg and foot knitting, the weight of the welt wires themselves and attached fabric, acting in combination with the fabric clearing action of the nibbed knock-over bits above described, provide an adequate take-up during the knitting of the remaining portion of the fabric blank.

The invention having been described, what is claimed is:

1. In a multiple section flat knitting machine, a machine frame including a work table extending along the front of the machine, knitting devices for each knitting section including a needle series and yarn measuring sinkers, actuating mechanism for the knitting devices including a cam shaft beneath the table, a welt mechanism including a welt bar for each knitting section having implements arranged for vertical and forward and back movements with relation to the needles to set up and to close the welt, and supporting and actuating structure for the welt bars comprising a welt cam shaft beneath the table, horizontally disposed welt bar vertical motion levers beneath the table, upwardly extending welt bar support arms pivoted from the vertical motion levers for forward and back movements, and cam and follower connections from the welt cam shaft for controlling the movements of said levers and arms.

2. In a multiple section flat knitting machine, a machine frame including a work table extending along the front of the machine, knitting devices for each knitting section including a needle series and yarn measuring sinkers, actuating mechanism for the knitting devices including a cam shaft beneath the table, a welt mechanism including a welt bar for each knitting section having implements arranged for vertical and forward and back movements with relation to the needles to set up and to close the welt, and supporting and actuating structure for the welt bars comprising a welt cam shaft beneath the table, horizontally disposed welt bar vertical motion levers beneath the table, a rock shaft mounted on the frame toward the front of the machine to which the vertical motion levers are secured, upwardly extending welt bar support arms pivoted from the vertical motion levers for forward and back movements with relation to the needles, cam and follower connections from the welt cam shaft for actuating said rock shaft, a welt vertical motion cam on the welt cam shaft, and a cam follower lever secured to the rock shaft engaging therewith, a welt forward and back motion rock shaft mounted on the frame, follower levers therefrom arranged to engage with and to move the welt bar supporting arms rearwardly, a take-up device including means for tensioning said arms and bar forwardly, a welt forward and back motion cam on the welt

cam shaft, and a follower lever from the forward and back motion rock shaft engaging therewith.

3. In a flat full fashioned type knitting machine having a machine frame including a work table extending along the front of the machine, knitting devices including a needle series and yarn measuring sinkers, and a welt bar which comprises a series of welt hooks having vertical shank portions and upwardly turned hook portions, a main cam shaft disposed beneath the table, a welt cam shaft between the table and main cam shaft, a welt bar vertical motion rock shaft located at the front of the machine below the table, a pair of welt bar vertical motion levers extending horizontally from the rock shaft beneath the welt cam shaft, a pair of upright welt bar supporting arms pivotally mounted on said levers rearwardly of the welt cam shaft, and cam and follower connections between the welt cam shaft and said respective welt bar vertical motion levers and welt bar supporting arms for imparting vertical and forward and back positioning movements to the welt hooks with relation to the needle series.

4. In a flat full fashioned type knitting machine having cross frames, and connecting rails including a sinker rail and a work table, knitting devices including a needle series and yarn measuring sinkers, and actuating mechanism including a main cam shaft located substantially beneath the table, a welt bar comprising implements movable relatively to the needles to form a setting up course of loops with the needles and to transfer the loops of the setting up course back to the needles to close the welt, a welt cam shaft disposed beneath the table and above the main cam shaft, a welt bar vertical motion rock shaft disposed along the front of the machine below the table, a pair of welt bar vertical motion levers extending horizontally from the rock shaft beneath the welt cam shaft, a pair of upright welt bar supporting arms pivoted on said levers rearwardly of the welt cam shaft and table, welt vertical and forward and back motion cams on the welt cam shaft, a vertical motion cam lever supported from the rock shaft, a forward and back motion rock shaft, actuating arms thereon to engage with and move rearwardly said welt bar supporting arms, and a welt forward and back motion cam lever supported from said forward and back motion rock shaft for actuating said arms.

5. In a flat full fashioned type knitting machine having cross frames, and connecting rails including a sinker rail and a work table, knitting devices including a needle series, yarn measuring sinkers, an actuating mechanism including a main cam shaft located substantially beneath the table, a welt bar comprising implements adapted for vertical and forward and back movements relatively to the needles to form a setting up course of loops with the needles and to transfer the loops of the setting up course back to the needles to close the welt, a welt cam shaft disposed beneath the table and above the main cam shaft, a welt bar vertical motion rock shaft disposed along the front of the machine below the table, a pair of welt bar vertical motion levers extending horizontally from the rock shaft beneath the table, a pair of upright welt bar supporting arms pivoted on said levers rearwardly of the table, welt vertical and forward and back motion cams on the welt cam shaft, a vertical motion cam lever supported from the rock shaft to engage the under side of its cam, spring means

urging the welt bar vertical motion levers upwardly, cam actuated levers arranged to engage against and to move the welt bar supporting arms backwardly, and a welt bar take-up device arranged for tensioning said supporting arms forwardly.

6. In a flat full fashioned type knitting machine having cross frames, and connecting rails including a sinker rail and a work table, knitting devices including a needle series, yarn measuring sinkers, and actuating mechanism including a main cam shaft located substantially beneath the table, a welt bar comprising implements arranged for vertical and forward and back movements relatively to the needles to form a setting up course of loops with the needles and to transfer the loops of the setting up course back to the needles to close the welt, a welt cam shaft disposed beneath the table and above the main cam shaft, a pair of horizontally disposed welt bar vertical motion levers disposed in the machine below the table level, cam and follower connections from the welt cam shaft for controlling the vertical position of the vertical motion levers, a pair of upright welt bar supporting arms extending upwardly between the table and the needle series, actuating levers arranged to engage with and to move the supporting arms backwardly, a cam and a yieldable follower connection therefrom for moving said actuating levers backwardly, and a welt bar take-up device exerting a take-up tensioning strain upon said supporting arms forwardly.

7. In a flat full fashioned type knitting machine having cross frames and connecting rails including a sinker rail and a work table, knitting devices including a needle series, and yarn measuring sinkers, actuating mechanism for the knitting devices including a main cam shaft located substantially beneath the table, a welt bar comprising implements adapted for vertical and forward and back movements relatively to the needles to form a setting up course of loops with the needles and to transfer the loops of the setting up course back to the needles to close the welt, a welt bar vertical motion rock shaft, a pair of horizontally disposed welt bar vertical motion levers supported from the rock shaft, vertically disposed welt bar supporting arms pivoted from said levers, operating means for imparting movements to said vertical motion levers and swinging movements to said supporting arms for setting up and closing the welt including actuating levers arranged to engage with and push rearwardly said welt bar and supporting arms, cam and follower connections for controlling the movement of said actuating levers, and a welt bar take-up device exerting a take-up tensioning strain upon said supporting arms forwardly.

8. In a flat full fashioned type knitting machine having cross frames and connecting rails including a sinker rail and a work table, knitting devices including a series of spring beard needles movable as a unit, a press edge, knockover bits, sinkers and dividing sinkers, a welt bar comprising implements movable relatively to the needles to form a setting up course of loops with the needles and to transfer the loops of the setting up course back to the needles to close the welt, actuating mechanism for said knitting instrumentalities including a main cam shaft located substantially beneath the table, a needle vertical motion rock shaft and a needle press motion rock shaft located beneath the table, a welt cam shaft disposed beneath the table and above the main

cam shaft, a welt bar vertical motion rock shaft disposed beneath and forwardly of the table, a catch bar and actuating connections therefor including a front catch bar lift motion rock shaft disposed beneath and rearwardly of the sinker rail.

9. In a flat full fashioned type knitting machine, a needle series, a welt bar comprising welt implements adapted for vertical and forward and back movements relatively to the needles to form a setting up course of loops with the needles and to transfer the loops of the setting up course back to the needles to close the welt, a pair of horizontally disposed welt bar vertical motion levers supported from the machine for up and down movement, a pair of vertically disposed welt bar supporting arms pivoted from said levers in the machine, cam and follower connections for controlling the up and down movement of the vertical motion levers, pusher devices for moving the supporting arms backwardly with relation to the needle series, a pair of backing up members and lever supports for locating said members to engage with and to limit the backward movement of said welt bar supporting arms, cam and follower connections positively supporting said backing up members against backward movement, and a welt bar take-up device exerting a take-up tensioning strain upon said supporting arms forwardly.

10. In a flat full fashioned type knitting machine, knitting devices including a series of spring beard needles, a press edge, yarn measuring sinkers and knockover bits, a welt bar comprising a series of vertically arranged welt hooks arranged to cooperate with alternate needles to press off from alternate needles and to place on the hooks the alternate needle loops and subsequently to return said loops to the needles to close the welt, a supporting structure for the welt bar comprising horizontally disposed vertical motion levers and forward and back motion welt bar supporting arms pivoted from the levers, actuating mechanism for the machine including mechanism for vertically positioning said levers and for moving the arms rearwardly to cooperate with the needles, backing up members movably supported in the machine to engage with and to limit the backward movement of the welt bar supporting arms and welt bar, and means controlled by said actuating mechanism for positioning said backing up members to limit positively the backward movement of the arms and welt bar.

11. In a flat full fashioned type knitting machine, knitting devices including a series of spring beard needles, a press edge, yarn measuring sinkers and knockover bits, a welt bar comprising a series of vertically arranged welt hooks arranged to cooperate with alternate needles to press off from alternate needles and to place on the hooks the alternate needle loops and subsequently to return said loops to the needles to close the welt, actuating mechanism for the knitting devices including a cam shaft, a supporting structure for the welt bar comprising horizontally disposed welt bar vertical motion levers and welt bar forward and back supporting arms pivotally mounted from said vertical motion levers, a welt cam and follower connections for controlling the position of said levers and arms including setting up positioning cams arranged to position the welt hooks to press off the alternate needles at a level substantially above the press edge of the machine, backing up members movably supported on the

machine to engage with and to limit the backward movement of the welt bar supporting arms and welt bar, and cam and follower connections for moving said backing up members to support said arms and welt bar during said needle press operation.

12. A claim according to claim 11 in which the cam and follower connections for the welt hooks and for the backing up members are constructed and arranged to cause the backing up members to provide a positive support for the supporting arms and welt bar during the pressing off of said alternate needle loops and thereafter during a forward and downward movement of the hooks to the shank side of the needles to engage the 15 cast off needle loops on the hooks.

13. In a flat full fashioned type knitting machine, knitting devices including a series of spring bearded needles, a press edge, yarn measuring sinkers and knockover bits, a welt bar having a longitudinally extending reinforcing rib, a series of vertically arranged welt hooks on the welt bar arranged to cooperate with alternate needles to press off from alternate needles and to place on the hooks the alternate needle loops and subsequently to return said loops to the needles to close the welt, a supporting structure for the welt bar comprising horizontally disposed vertical motion levers and forward and back motion welt bar supporting arms pivoted from the levers, actuating mechanism for the machine including mechanism for vertically positioning said levers and for moving the arms rearwardly to cooperate with the needles, backing up members movable to engage with and to limit positively the backward movement of the welt bar supporting arms and welt bar, and means controlled by said actuating mechanism for positioning said backing up members to support said arms, welt bar and hooks away from the press edge for said alternate needle press operation.

14. In a flat full fashioned type knitting machine having cross frames and connecting rails including a sinker rail and a work table, knitting devices including a series of needles, and actuating mechanism for the knitting devices including a main cam shaft located below the table, a welt bar comprising implements movable relatively to the needles to form a setting up course of loops with the needles and to transfer the loops of the setting up course back to the needles to close the welt, a welt cam shaft disposed below the table and above the main cam shaft, a pair of horizontally disposed welt bar vertical motion levers supported from the machine below the table, a pair of welt bar supporting arms pivoted from said levers and extending above the table, cam and follower connections from the welt cam shaft for controlling the movement of the vertical motion levers, pusher devices arranged to act against the supporting arms to move the arms rearwardly, cam and follower connections from the welt cam shaft for actuating the pusher devices, a welt bar take-up device exerting a take-up tensioning strain upon said supporting arms forwardly, a pair of backing up members including lever supports movable to engage the backing up members with said welt bar supporting arms at substantially the level of the welt bar, and cam and follower connections for positively positioning the lever supports and backing up members against the supporting arms.

15. In a flat full fashioned type knitting machine having cross frames and connecting rails including a sinker rail and a work table, knitting

devices including a needle series and actuating mechanism including a main cam shaft located substantially beneath the table, a welt bar comprising a series of welt hooks having vertical shank portions and upwardly turned hook portions adapted during the setting up course to engage with and press the beards of alternate needles and thereafter to engage the cast off needle loops on the hooks to the shank sides of the needles, and upon completion of the welt knitting to transfer the said setting up loops back to the needles, a welt cam shaft disposed beneath the table, a pair of horizontally disposed welt bar vertical motion levers supported from the machine below the table, a pair of upwardly extending supporting arms pivoted from said levers for positioning the welt bar above the table, cam and follower connections from the welt cam shaft for controlling the vertical position of the said vertical motion levers, actuating pusher levers arranged to engage with and move the supporting arms backwardly, a cam on the welt cam shaft and a yieldable follower connection therefrom for moving said actuating levers backwardly, a pair of backing up members to engage with and to limit the backward movement of said welt bar supporting arms, cam and follower connections from the welt cam shaft positively supporting said backing up members against backward movement, and a welt bar take-up device for exerting a take-up tensioning strain upon said supporting arms forwardly.

16. In a flat full fashioned type knitting machine having cross frames and connecting rails including a sinker rail and a work table, knitting devices including a needle series and actuating mechanism including a main cam shaft located substantially beneath the table, a welt bar comprising implements movable relatively to the needles to form a setting up course of loops with the needles and to transfer the loops of the setting up course back to the needles to close the welt, a welt bar vertical motion rock shaft and horizontally disposed welt bar vertical motion levers supported from the rock shaft beneath the table, upwardly extending welt bar support arms pivoted from the levers for mounting the welt bar above the table level, a welt bar forward and back motion rock shaft disposed rearwardly of the table and pusher levers mounted thereon to act against the respective support arms, cam and follower connections arranged to act yieldably against said forward and back motion rock shaft and pusher levers, a backing up rock shaft and a pair of backing up plates and lever supports mounted from the backing up rock shaft to engage with and to limit backward movement of the welt bar supporting arms, backing up cam and follower connections arranged to positively support said backing up rock shaft and plates against backward movement, and a welt bar take-up device exerting a take-up tensioning strain upon said supporting arms forwardly.

17. In a multiple section flat knitting machine, a machine frame including a work table, knitting devices for each knitting section including a spring bearded needle series, a press edge, and yarn measuring sinkers, actuating mechanism for the knitting devices including a cam shaft, a welt mechanism including a welt bar for each knitting section having vertical hooks arranged to press off the loops from alternate needles and to engage said loops on the hooks to form an alternate needle set up on the hooks and needles, and thereafter to return the loops to the needles to turn

the welt, supporting and actuating structure for the welt bars comprising a welt cam shaft below the table, horizontally disposed welt bar vertical motion levers beneath the table, upwardly extending welt support arms pivoted from the vertical motion levers for forward and back movements, a welt vertical motion rock shaft, and welt cam and follower connections for controlling the vertical motion levers, a welt forward and back rock shaft, and pusher levers yieldably actuated thereby for moving the support arms rearwardly, backing up members arranged to engage with and limit backward movement of the welt bars and supporting arms, a rock shaft on which said backing up members are carried, and cam and follower connections from the welt cam shaft for actuating said backing up rock shaft.

13. In a flat knitting machine having knitting devices including a needle series, a welt bar having welt implements, actuating mechanism for the knitting devices, mechanism for moving the welt bar to bring the welt implements into operative relation to the needles, and means for accurately positioning the welt bar and welt implements longitudinally of the needle series when in operative relation thereto comprising a fin mounted on the midportion of the welt bar and cooperating relatively stationary abutments on the machine for engagement with opposite sides of the fin.

19. In a flat knitting machine having knitting devices including a needle series, a welt bar having welt implements, actuating mechanism for the knitting devices, mechanism for moving the welt bar to bring the welt implements into operative relation to the needles, and means for accurately positioning the welt bar and welt implements longitudinally of the needle series when in operative relation thereto comprising a fin and a pair of spaced abutments between which the fin engages for the operative position of the welt implements relative to the needles, one of said fin and pair of abutments being supported from the welt bar midway of the length thereof and the other of said fin and pair of abutments being supported on the machine.

20. In a flat knitting machine, knitting devices including a needle series and yarn measuring sinkers, a welt bar having vertically arranged hooks cooperating with the needles to set up and to close the welt, supporting and actuating structure for the welt bar comprising horizontally disposed welt bar vertical motion levers and vertically disposed welt bar supporting arms pivoted from the levers, actuating mechanism for the machine including cam and follower connections acting upon said respective levers and arms for moving the welt bar and hooks into operative relation to the needles, and means for accurately positioning the welt bar and hooks longitudinally of the needle series when in operative relation thereto comprising a fin and a pair of spaced abutments between which the fin engages for the operative position of the hooks relative to the needles, one of said fin and pair of abutments being supported from the welt bar midway of the length thereof and the other of said fin and pair of abutments being supported on the machine.

21. In a multiple section flat knitting machine, a machine frame including a work table extending along the front of the machine, knitting devices for each knitting section including a needle series and yarn measuring sinkers, a narrowing machine including an axially shiftable pivot point support rod upon the narrowing machine, actuating mechanism for the knitting devices includ-

ing a cam shaft beneath the table, a welt mechanism including a welt bar for each knitting section having implements to cooperate with the needles to set up and to close the welt, supporting and actuating structure for the welt bars comprising horizontally disposed welt bar vertical motion levers and vertically disposed welt bar support arms pivoted from said levers, actuating mechanism for the welt bar including welt cam and follower connections for controlling said levers and arms to move the welt bar and implements into operative relation to the needles, and means for accurately positioning the welt bar and implements longitudinally of the needle series

10 when in operative relation thereto comprising a fin and a pair of abutments between which the fin engages for the operative position of the welt hocks relative to the needles, one of said fin and pair of abutments being supported from the welt bar midway of the length thereof and the other of said fin and pair of abutments being supported on said pivot point support rod.

22. In a flat knitting machine having a machine frame including a sinker rail and a work table 25 extending along the length of the machine, knitting devices including a needle series, and yarn measuring sinkers, mechanism for the knitting devices including a cam shaft, a welt bar comprising a series of welt implements arranged for vertical and forward and back movements with relation to the needles to form a setting up course of welt fabric with the needles and thereafter to return said loops to the needles to close the welt, supporting structure for the welt bar comprising 30 a pair of horizontally disposed welt bar vertical motion levers located below the table, welt bar supporting arms pivoted from said levers for supporting said welt bar above the table, welt bar actuating mechanism including welt cam and follower connections for controlling the movements of said levers and arms to set up and to close the welt, and releasable holding devices connecting the lever arms and said welt bar to permit the ready removal of the welt bar from the 35 machine.

23. In a multiple section flat full fashioned knitting machine, a machine frame comprising cross frames and tie rails including a sinker rail and a work table extending along the length of the machine, knitting devices including for each knitting section a needle series and yarn measuring sinkers, actuating mechanism for the knitting devices including a cam shaft, a welt bar for each knitting section, horizontally disposed welt 50 bar vertical motion levers located below the table, upwardly extending welt bar supporting arms pivotally mounted on said levers for forward and back movement, a welt cam shaft disposed below the table and cam and follower connections from the welt cam shaft for controlling the movements of said levers and arms to set up and to close the welt, and releasable holding devices connecting the lever arms and said welt bar to permit the ready removal of each welt bar individually from the machine.

24. In a flat knitting machine having a needle series, a welt mechanism cooperating with the needle series comprising a welt bar having welt implements movable relatively to the needles to form a setting up course of welt fabric with the needles and thereafter to return the loops to the needles to close the welt, and supporting and actuating structure for the welt bar including a pair of movable welt bar supporting arms and releasable holding devices for rigidly connecting

said supporting arms with the two ends of the welt bar, each holding device comprising a pair of parallel laterally converging holding surfaces and a transverse end blocking surface on the supporting arm, corresponding engaging laterally converging side surfaces and an end block surface on said welt bar, and a wedge shaped locking element movably mounted on one of said supporting arm and welt bar for movement longitudinally of the welt bar for wedging together said holding and corresponding engaging surfaces.

25. In a flat knitting machine having a needle series, a welt mechanism cooperating with the needle series comprising a welt bar having welt implements movable relatively to the needles to form a setting up course of welt fabric with the needles and thereafter to return the loops to the needles to close the welt, and supporting and actuating structure for the welt bar including a pair of movable welt bar supporting arms and releasable holding devices for rigidly connecting said supporting arms with the two ends of the welt bar, each holding device comprising a pair of parallel laterally converging holding surfaces and a transverse end blocking surface on the supporting arm, corresponding engaging laterally converging side surfaces and an end block surface on said welt bar, a wedge shaped aperture formed in the end of the welt bar, a wedge shaped locking member shiftable on the supporting arm into engagement with said aperture for securing the cooperating tapered surfaces and said end blocking surfaces of the bar and supporting lever arms together, and spring means urging said locking member into said locking position.

26. In a flat full fashioned type knitting machine, knitting devices including a needle series, an actuating mechanism including a main cam shaft, a welt bar comprising implements movable relatively to the needles to form a setting up course of loops with the needles and to transfer the loops of the setting up course back to the needles to close the welt, a welt cam shaft, supporting and actuating mechanism for the welt bar comprising a pair of horizontally disposed welt bar vertical motion levers, a pair of vertically arranged welt bar supporting arms pivoted from said levers for forward and back movement with relation to the needles, releasable holding devices connecting the lever arms and said welt bar to permit the ready removal of the welt bar from the machine each comprising cooperating holding surfaces on the arm and welt bar, a removable wedge locking member supported on one of said arm and welt bar, and a cooperating wedge locking surface on the other of said arm and welt bar.

27. In a flat knitting machine, knitting instrumentalities including a series of spring beard needles movable as a unit, a press edge, yarn measuring sinkers, actuating mechanism for the machine including devices for imparting longitudinal and forward and back movements to the needles with relation to the press edge, positioning means for controlling the forward and back position of the needles for the sinking of yarn about the needles by the yarn measuring sinkers, a welt mechanism including welt instrumentalities operable to form a setting up course on said instrumentalities and on alternate needles, and devices operative during the knitting of a setting up course to condition said needle positioning means to position the needles for the measuring of setting up needle wale kinks

of a size substantially smaller than required for a normal tight stitch.

28. In a flat knitting machine, knitting instrumentalities including a series of spring beard needles movable as a unit, a press edge, yarn measuring sinkers, actuating mechanism for the machine including a main cam shaft and cam and follower connections therefrom including a needle press cam, a welt mechanism including welt instrumentalities operable to form a setting up course on said instrumentalities and on alternate needles, and devices including a setting up needle press cam operative during the knitting of a setting up course to position the needles for the measuring of setting up needle wale kinks of a size substantially smaller than required for a normal tight stitch, and thereafter to move the needles to a press position substantially above the normal press level.

29. In a flat full fashioned knitting machine, knitting instrumentalities including a series of spring beard needles movable as a unit, a press edge, yarn measuring sinkers, actuating mechanism for imparting vertical and forward and back movements to the needles with relation to the press edge, stitch regulator mechanism for the machine including a device operable to position the needles forwardly for the sinking of abnormally small sinker wale loops, a welt mechanism including welt instrumentalities operable to form a setting up course on said instrumentalities and on alternate needles, and devices for conditioning said needle actuating mechanism and regulator mechanism to position the needles for the measuring of setting up needle wale kinks of a size substantially smaller than required for a normal tight stitch.

30. In a flat full fashioned knitting machine, knitting instrumentalities including a series of spring beard needles movable as a unit, a press edge, yarn measuring sinkers, actuating mechanism for imparting vertical and forward and back movements to the needles with relation to the press edge including a needle setting up press cam, stitch regulator mechanism for the machine including a device acting when rendered operative to position the needles forwardly for the sinking of abnormally small sinker wale loops, a welt mechanism comprising a welt bar having a series of vertically disposed welt hooks spaced to cooperate with alternate needles, and operating mechanism for the welt bar operable in accordance with a setting up cycle of operations to press off alternate needles above said press edge and thereafter to engage the cast-off loops on said hooks, and devices for conditioning said needle actuating mechanism and stitch regulator mechanism to position the needles for the measuring of setting up needle wale kinks of a size substantially smaller than required for a normal tight stitch.

31. In a flat full fashioned knitting machine, knitting instrumentalities including a series of spring beard needles movable as a unit, a press edge, yarn measuring sinkers, actuating mechanism for the machine including a main cam shaft, cam and follower connections therefrom for actuating the needles including a needle press cam, and a needle setting up press cam arranged to move the needles to a press position substantially above the normal press edge engaging position, a stitch regulator mechanism, a special setting up stitch regulator mechanism arranged to position the needles for the formation of setting up needle wale kinks of a size substantially

smaller than required for the knitting of a normal tight stitch, a welt bar comprising a series of welt hooks spaced to cooperate with alternate needles, operating mechanism for the welt bar arranged to position the welt hooks to press off alternate needles substantially above the level of the press edge and thereafter to engage said alternate needle wale loops on the hooks, and a pattern control device for rendering said welt mechanism, said special setting up press cam and said special setting up stitch regulator mechanism operative for the knitting of a setting up course of welt fabric.

32. In a flat full fashioned knitting machine, knitting devices including a series of needles movable as a unit, yarn measuring sinkers and knockover bits having nibbed portions for clearing the fabric as knitted to the backs of the needles, welt devices operable to form a setting up course of loops with the needles and thereafter to return the initial loops to the needles to close the welt, a fabric takeup to engage with and take up a fold of the welt fabric including, with a welt wire, a pair of welt wire engaging hooks, a welt wire take-up device connected to move the hooks to draw off a portion only of the length of the fabric to be knitted, a slide on which the knitted fabric is supported extending in a generally forward and downward direction from the needles, and means for limiting the movement of the fabric take-up including the welt wire engaging hooks whereby the fabric take-up is effected during continued knitting by the weight of the fabric and attached welt wire and by the clearing action of the nibbed knockover bits.

33. In a flat full fashioned knitting machine, knitting devices including a series of needles movable as a unit, yarn measuring sinkers and knockover bits having nibbed portions for clearing the fabric as knitted to the backs of the needles, welt devices operable to form a setting up course of loops with the needles and thereafter to return the initial loops to the needles to close the welt, a fabric take-up to engage with and take up a fold of the welt fabric including, with a welt wire, a pair of welt wire engaging hooks, a welt wire take-up device connected to move the hooks to draw off a portion only of the length of the fabric to be knitted, means for relatively moving the welt wire support and take-up hooks to engage the hooks with the welt wire and to take up a fold of welt fabric, a slide on which the knitted fabric is supported extending in a generally forward and downward direction from the needles, and means for limiting the movement of the fabric take-up including the welt wire engaging hooks whereby the fabric take-up is effected during continued knitting by the weight of the fabric and attached welt wire and by the clearing action of the nibbed knockover bits.

34. In a flat full fashioned knitting machine, knitting devices including a series of needles movable as a unit, yarn measuring sinkers and knockover bits having nibbed portions for clearing the fabric as knitted to the backs of the needles, welt devices operable to form a setting up course of loops with the needles and thereafter to return the initial loops to the needles to close the welt, a fabric take-up to engage with and take up a fold of the welt fabric including, with a welt wire, a fabric draw-off shaft, welt wire engaging implements and flexible connectors between the draw-off shaft and welt wire engag-

ing implements constructed and arranged to draw off a portion only of the length of the fabric to be knitted in a forward and thereafter in a downward direction, a hopper into which the welt wire and attached fabric is delivered by said take-up device, and a fabric take-up resetting device having a stepped operation to move the said flexible connectors and implements in a reverse direction, and control means controlled by movement of the flexible connectors in the take-up direction to render said resetting device operative and by movement of said flexible connectors and implements to the reset position to render said resetting device inoperative.

15 35. In a flat full fashioned knitting machine, knitting devices including a series of needles movable as a unit and elements cooperating with the needles to clear the fabric as knitted to the backs of the needles, welt devices arranged to cooperate with the needles to form a setting up course of loops with the needles and thereafter to return the initial loops to the needles to close the welt, a fabric take-up to engage with and take up a fold of the welt fabric including, with a welt wire, a fabric draw-off shaft, welt wire engaging implements, and flexible connectors between the draw-off shaft and welt wire engaging implements, constructed and arranged to draw off a portion only of the length of the fabric to be knitted in a forward and thereafter in a downward direction, a hopper to which the welt wire and attached fabric are delivered by said welt wire engaging implements and flexible connectors and a fabric take-up resetting device arranged to move the flexible connectors and welt wire engaging implements in a reverse direction during the continued knitting and moving of the fabric as knitted into said hopper.

36. In a flat full fashioned knitting machine, 40 knitting devices including a series of needles movable as a unit and elements cooperating with the needles to clear the fabric as knitted to the backs of the needles, welt devices arranged to cooperate with the needles to form a setting up course of loops with the needles and thereafter to return the initial loops to the needles to close the welt, a fabric take-up to engage with and take up a fold of the welt fabric including a fabric draw-off shaft, welt wire engaging implements, and flexible connectors between the draw-off shaft and the welt wire engaging implements constructed and arranged to draw off a portion only of the length of the fabric to be knitted in a forward and thereafter in a downward direction, a hopper to which the welt wire and attached fabric are delivered by said take-up device, means for applying a tensioning torque to the draw-off shaft in the take-up direction, a fabric take-up resetting device having a stepped operation to move the flexible connectors and welt wire engaging implements in a reverse direction, a latching device for supporting the flexible connectors and welt wire engaging implements in a reset position, and strip devices rendered operative by continued movement of the flexible connectors and welt wire engaging implements in the take-up direction to render said reset mechanism operative, and by the return of the take-up to reset position to render said resetting device inoperative.

37. In a flat knitting machine the combination with knitting devices comprising a press edge, a series of spring beard needles movable longitudinally and forward and back with relation to the press edge, yarn measuring sinkers,

51

and a series of knocking over elements, a knocking over element bar, spring means urging the knocking over element bar upwardly and forwardly, positioning devices movable for positively limiting upward and forward movement of the knocking over element bar, an additional knocking over element positioning device movable to limit downward movement of the knocking over element bar, and cam means for positioning said devices arranged to provide alternately a solid and a spring seated support for the knocking over element bar against movement downwardly.

38. In a flat knitting machine the combination with knitting devices comprising a press edge, a series of spring beard needles movable longitudinally and forward and back with relation to the press edge, yarn measuring sinkers and a series of knocking over elements, a knocking over element bar, spring means urging the knocking over element bar upwardly, positioning devices movable for positively limiting upward movement of the knocking over element bar, an additional knocking over element bar positioning device movable to limit downward movement of the knockover bar, and cam means for positioning said devices arranged to provide a positive support for the knocking over element bar vertically in both directions during downward and press movement of the needles and a spring seated support for the knocking over element bar against movement downwardly for the knocking over position of the needles.

39. A machine according to claim 38 in which there is provided a narrowing machine and cam means for operating the knitting devices in accordance with a narrowing cycle of operation which includes knocking over element bar operating cams for controlling said knocking over element bar, positioning devices to maintain a continuously positive support of said knocking over element bar vertically in both directions during the narrowing cycle of operation.

40. In a flat knitting machine, the combination with knitting devices comprising a press edge, a series of spring beard needles movable longitudinally and forward and back with relation to the press edge, yarn measuring sinkers, and a series of knocking over elements, a knocking over element bar, spring means urging the knocking over element bar upwardly, and positioning devices movable for positively limiting the vertical movement of the knocking over element bar comprising pivots on the knocking over element bar, a pair of rocker levers providing upper and nether part bearings for each pivot, and cam means for controlling the positions of said levers to provide a positive support for the knocking over element bar vertically in both directions, and alternately a spring seated support for the knocking over element bar against movement downwardly.

41. In a flat knitting machine, the combination with knitting devices comprising a press edge, a series of spring beard needles movable longitudinally and forward and back with relation to the press edge, yarn measuring sinkers, and a series of knocking over elements, a knocking over element bar providing pivots about which the knocking over element bar is arranged for forward and back swinging movement, spring means urging the knockover element bar upwardly and forwardly, and positioning devices for the knocking over element bar comprising a pair of knocking over vertical motion rock shafts, a

52

pair of rocker levers mounted one on each rock shaft and providing cooperating upper and nether part bearings for each pivot, a knocking over element forward and back motion rock shaft, upwardly extending arms supported therefrom to engage with and limit the forward movement of the knocking over element bar, and cam and follower connections for actuating all of said rock shafts to provide a positive support for the knocking over element bar vertically, and alternately a spring seated support for the knocking over element bar downwardly, and a spring seated support for the knocking over element bar forwardly.

42. In a flat full fashioned knitting machine, 15 knitting devices including a series of needles movable as a unit, yarn measuring sinkers, a yarn carrier movable from an idle position at one end of the needle series to feed yarn, a yarn clamp, a yarn cutter arranged to cut the yarn extending 20 from the clamp to the feeding carrier, and a yarn guide for guiding a portion of the yarn extending from the clamp to the carrier into the path of the cutter.

43. In a flat full fashioned knitting machine, 25 knitting devices including a series of needles, a yarn carrier movable from an idle position at one end of the needle series to feed yarn, a yarn clamp in which is engaged the end of yarn leading from the idle carrier, a yarn guide about which the 30 thread passes from the clamp to the carrier when moved from said idle position to feed yarn, and a yarn cutter arranged to sever a portion of yarn positioned by said yarn guide.

44. In a multiple section flat full fashioned 35 knitting machine knitting devices associated with each section including a series of needles movable as a unit, yarn measuring sinkers, a yarn carrier movable from idle position at one end of the needle series for feeding yarn, a yarn clamp for holding the end leading from the idle carrier, a yarn guide adjacent the end of the needle series for engaging the yarn extending from the clamp to the feeding carrier, a thread cutter disposed between the guide and the needle series, and means acting when rendered operative for simultaneously actuating the cutters associated with the several knitting sections.

45. In a flat knitting machine, knitting devices including a series of needles, a yarn carrier movable from an idle position at one end of the needle series, a yarn clamp, and a yarn cutter including an anvil surface, and a pivoted knife blade arranged to sever a portion of the yarn leading from the clamp to the yarn carrier when moved from 50 said idle position, spring means for actuating the knife, a latch for normally supporting the knife blade in a retracted position against the pressure of said spring, and an actuating and reset mechanism arranged to trip the latch to sever the thread and thereafter to return the knife to the latch engaging position.

46. In a flat knitting machine, knitting devices including a series of needles, a yarn carrier movable from an idle position at one end of the needle 55 series, a welt mechanism comprising welt instrumentalities cooperating with the needles to form a setting up course of loops with the needles, and thereafter to return said loops to the needles to close the welt, a fabric take-up comprising, with 60 a welt wire, a pair of welt wire engaging take-up hooks, a take-up shaft, a pair of flexible connectors between the take-up hooks and shaft, means for supporting said connectors and welt wire take-up hooks in a pre-set welt wire en- 70 gaging position, a yarn clamp, and a yarn cutter

including an anvil surface and a pivoted knife blade arranged to sever a portion of the yarn leading from the clamp to the yarn carrier when moved from said idle position, spring means for actuating the knife, a latch for normally supporting the knife blade in a retracted position against the pressure of said spring, and trip and reset connections from the flexible connectors and welt wire take-up hooks rendered operative by a rearward movement of the hooks and connectors from said pre-set position to trip the cutter, and by a forward movement of the hooks to reset the cutter.

47. In a flat knitting machine, knitting devices including a series of needles, a yarn carrier movable from an idle position at one end of the needle series, a welt mechanism comprising welt instrumentalities cooperating with the needles to form a setting up course of loops with the needles, and thereafter to return said loops to the needles to close the welt, a fabric take-up comprising, with a welt wire, a pair of welt wire engaging take-up hooks, a take-up shaft, a pair of flexible connectors between the take-up hooks and shaft, means for applying a take-up tensioning torque to the take-up shaft, means for turning the shaft in a direction opposite to said tensioning strain against and for moving the take-up hooks rearwardly, a yarn clamp, a thread cutter operable to cut a portion of the thread extending from the clamp to the yarn carrier, and means rendered operative by a rearward movement of the take-up hooks to operate the cutter.

48. In a multiple section flat full fashioned knitting machine knitting devices associated with each section including a series of needles movable as a unit, yarn measuring sinkers, a yarn carrier movable from an idle position at one end of the needle series for feeding yarn, a yarn clamp for holding the end leading from the idle carrier, a yarn cutter comprising a knife operable to sever the yarn extending from the clamp to the carrier, a fabric take-up comprising, with a welt wire, welt wire engaging hooks and flexible connectors for moving the hooks forwardly in a draw-off direction and rearwardly to a welt wire engaging position, a knife actuating device associated with an adjacent take-up hook rendered operative by movement of the take-up hook rearwardly to sever the yarn, and mechanism for imparting simultaneous rearward movements to the take-up hooks associated with the several knitting sections to sever the yarn ends leading from the respective carriers.

49. In a flat full fashioned knitting machine knitting devices including a series of needles movable as a unit and yarn measuring sinkers, a narrowing machine, a picot bar, a picot shift rod on the narrowing machine on which the picot bar is mounted for longitudinal shifting movement to form the picot, actuating mechanism for the machine including a main cam shaft shiftable between knitting and narrowing positions, a picot shift mechanism including a cam and follower connections operative for the narrowing position of the cam shaft to shift the picot bar, a pattern mechanism for the machine, and a pattern controlled device for rendering said picot shift mechanism inoperative for the narrowing position of the cam shaft.

50. In a flat full fashioned knitting machine, knitting devices including a series of needles movable as a unit and yarn measuring sinkers, a narrowing machine arranged for dipping move-

ments in accordance with a narrowing cycle of operation, a picot bar, a picot shift rod on the narrowing machine on which the picot bar is mounted for longitudinal shifting movement to form the picot, actuating mechanism for the machine including a main cam shaft shiftable between knitting and narrowing positions, a picot shift mechanism including cam and follower connections from the cam shaft operative for the narrowing position of the cam shaft to shift the picot rod, a pattern mechanism for the machine, a pattern shift rod shiftable to render the picot shift mechanism inoperative, a latch device for supporting the pattern rod in the shifted position, and a connection rendered operative by a dipping movement of the narrowing machine to release the latch.

51. In a flat full fashioned type knitting machine, knitting devices including a needle series, actuating mechanism for the knitting devices including a cam shaft, a welt bar comprising a series of vertically arranged welt hooks arranged for vertical and forward and back movements with relation to the needles to form a setting up course with the needles, to draw off the fabric as knitted, and thereafter to return the loops to the needles to close the welt, a fabric take-up comprising, with a welt wire, fabric take-up members adapted with the welt wire to engage with and take up a fold of the welt fabric, supporting and actuating structure for the welt bar comprising horizontally disposed welt bar vertical motion levers located beneath the table, upwardly extending welt bar support arms pivoted from the vertical motion levers, means for controlling the positions of said levers and arms to set up and to turn the welt, and additional means for controlling the vertical position of said vertical motion levers to maintain one position of said levers during the knitting of the first welt courses and thereafter in a higher position for the knitting of further welt courses.

52. In a flat full fashioned type knitting machine, knitting devices including a needle series, actuating mechanism for the knitting devices including a cam shaft, a welt bar comprising a series of vertically arranged welt hooks arranged for vertical and forward and back movements with relation to the needles to form a setting up course with the needles, to draw off the fabric as knitted, and thereafter to return the loops to the needles to close the welt, a fabric take-up comprising, with a welt wire, fabric take-up members adapted with the welt wire to engage with and take up a fold of the welt fabric, supporting and actuating structure for the welt bar comprising horizontally disposed welt bar vertical motion levers located beneath the table, upwardly extending welt bar support arms pivoted from the vertical motion levers, means for controlling the positions of said levers and arms to set up and to turn the welt, mechanism acting when rendered operative to cause the fabric take-up to engage with and take up the fold of welt fabric, and a latching device operable during the knitting of initial welt courses for latching the vertical motion levers in a relatively low take-up position and operable prior to the operation of the fabric take-up for supporting said vertical motion levers in a higher position.

53. In a flat full fashioned type knitting machine, a machine frame including a work table extending longitudinally of the machine, knitting devices including a needle series and yarn measuring sinkers, actuating mechanism including a

cam shaft for actuating the knitting devices, a welt bar comprising a series of welt hooks with vertical shanks and upwardly turned hooks, supporting and actuating structure for the welt bar comprising horizontally disposed welt bar vertical motion levers located beneath the table, upwardly extending welt bar support arms pivoted from the vertical motion levers, welt vertical motion cam and follower connections arranged for moving the supporting arms positively downwardly, spring means acting to move said vertical motion levers upwardly, forward and back motion cam and follower connections for controlling the forward and back position of said arms, and a latching device acting when rendered operative to position the vertical motion levers against downward movement under the influence of said spring means.

54. In a flat full fashioned type knitting machine, a knitting machine frame including a work table extending along the length of the machine, knitting devices including a series of needles movable as a unit, yarn measuring sinkers and knockover bits, actuating mechanism for the knitting devices including a cam shaft, a welt bar comprising a series of vertically arranged welt hooks arranged to cooperate with alternate needles to cast off from alternate needles and to place on the hooks the alternate needle loops and subsequently to return said loops to the needles to close the welt, supporting and actuating structure for the welt bar comprising horizontally disposed welt bar vertical motion levers and vertically disposed welt bar support arms pivoted from the vertical motion levers, a fabric take-up arranged to swing the support arms forwardly to take up the welt fabric as knitted, a welt cam shaft, welt vertical and forward and back motion cams on the cam shaft,

5

10

and follower connections for controlling the vertical and forward and back position of the welt hooks to set up and to close the welt including a vertical motion cam follower arranged to move the vertical motion lever positively downwardly, spring means tending to move the vertical motion lever upwardly, and a latching device operable upon completion of the setup for latching the vertical motion levers and the welt hook in position with the hooks between the knockover bits.
